ABSTRACT: A character generator is described for producing deflection of a beam in a cathode-ray tube to generate selected characters on its screen. Deflection information representing the selected character is generated by a set of wires (one set for each character) wound on a series of magnetic cores and is read out by sequential energization of the cores. The signals produced by the set are utilized to control charging circuits which produce constant current output signals of appropriate sign representing increments of beam deflection to generate the selected character. The output signals are accumulated by a pair of storage means which are respectively adapted for connection to the horizontal and vertical deflection means of the cathode-ray tube.

CHARACTER GENERATOR

This invention relates to character generators for use with cathode-ray tubes having deflection plates or deflection coils. More particularly, the invention relates to a character generator which generates deflection voltages for cursorily writing characters, rather than deflection voltages representative of a raster scan or other type of fixed pattern scan.

Cathode-ray tubes are frequently utilized in connection with electronic computers for providing a display of information representative of the output of the computer. Synthesis of characters by providing appropriate deflection voltages to suitable deflection devices in a cathode-ray tube may be accomplished by several different techniques. One such technique involves causing the cathode-ray tube to be deflected through a raster scan or other type of fixed pattern scan which is the same for all characters. The cathode-ray tube beam is allowed to impinge upon the tube screen only at certain times during the scan, such as by appropriate variations of grid voltage, depending upon the particular character being generated. This character generation technique has the disadvantage that a fixed and relatively long period of time is required for each character, irrespective of the complexity or simplicity of the character being generated. Thus a considerable amount of time is wasted due to the necessity of completing the full scan for each character.

In order to more efficiently utilize time, techniques have been developed for character generation in which deflection voltages are produced for writing the characters cursorily, rather than by utilizing a raster scan or other type of fixed pattern scan. Such techniques typically form the characters in a series of dots or strokes, suitable provision being made for blanking the electron beam at appropriate times, although most of the alphabetic and numeric characters can be generated without such blanking during the generation of the character. Character generators utilizing such cursive writing techniques include provision for storing a considerable amount of information, depending upon the complexity and number of characters to be generated.

Many character generators of the cursive writing type incorporate a number of magnetic, resistive or diode devices interconnected by a wiring pattern. Either the state of the devices or the configuration of the wiring pattern serves for storing the character shape information. Such generators also incorporate logic circuitry utilizing analytic techniques for producing the required deflection voltages from the information in the storage devices. Typically such character generators require a relatively large number of devices or a complex wiring pattern and, as the number of characters or the complexity of the characters increases, a corresponding increase in the complexity of the character generator results. Moreover, such types of character generators sometimes suffer from poor character registration, uneven intensities and discontinuities between various parts of characters, and are typically limited in the available character styles which may be produced. Furthermore, many known information storage and readout systems for character generators are subject to undesired interference from signals representative of unselected characters.

It is an object of this invention to provide an improved character generator for use with a cathode-ray tube.

Another object of the invention is to provide a character generator in which the required number of components per character is reduced over heretofore known devices of corresponding capability.

A further object of the invention is to provide a character generator which utilizes a simple and low cost means of information storage.

Still another object of the invention is to provide a character generator in which character selection is accomplished with minimal interference from unselected characters.

It is a further object of the invention to provide a character generator which utilizes cursive writing of characters rather than a raster scan or other type of fixed pattern scan, and which provides good character registration, even intensities and continuity between various parts of characters, and freedom in design of character styles.

Other objects of the invention will become apparent to those skilled in the art from the following detailed description, taken in connection with the accompanying drawings wherein:

- 5 FIG. 1 is a block diagram of a character generator constructed in accordance with the invention and illustrating, schematically, a cathode-ray tube used in connection therewith;
- 10 FIG. 2 is an illustration of the character G as formed by utilizing the character generator illustrated in FIG. 1 as a dot-type generator;
- 15 FIG. 3 is a series of graphs illustrating the operation of the character generator of FIG. 1 in producing the character G as illustrated in FIG. 2;
- 20 FIG. 4 is an illustration of a dot sequence of the character V produced by the character generator of FIG. 1 utilized as a dot-type generator as it would appear on the cathode-ray tube screen (a) without the proportioning circuit, and (b) with the proportioning circuit;
- 25 FIG. 5 is a circuit diagram of part of the apparatus as FIG. 1 in a configuration for dot-type character generation;
- 30 FIG. 6 is a circuit diagram illustrating a stage in one type of pulse generator which may be utilized in the character generator of FIG. 1;

- 55 FIG. 11 is a diagram illustrating the available strokes when the character generator of FIG. 1 is utilized as a stroke-type character generator;
- 60 FIG. 12 is an illustration of the letter C as formed by utilizing the character generator of FIG. 1 as a stroke-type character generator;
- 65 FIG. 13 is a series of graphs illustrating the operation of the character generator of FIG. 1 as a stroke-type generator to produce the letter C as illustrated in FIG. 12;
- 70 FIG. 14 is a circuit diagram of a portion of an externally timed sequential pulse generator which may be used in the character generator of FIG. 1;
- 75 FIG. 15 is a circuit diagram of a portion of a charging circuit which may be utilized in the character generator of FIG. 1 for producing characters by the stroke-type generation illustrated in FIGS. 12 and 13;
- 80 FIG. 16 is a circuit diagram of an intensity circuit as may be utilized in the character generator of FIG. 1 for stroke-type character generation of characters as illustrated in FIGS. 12 and 13;
- 85 FIG. 17 is a block diagram of another embodiment of the invention;
- 90 FIG. 18 is a block diagram of a further embodiment of the invention;
- 95 FIG. 19 is a diagram illustrating the available strokes in the embodiment of FIG. 18;
- 100 FIG. 20 is a circuit diagram of a charging current generator which may be utilized in the embodiment of FIG. 18;
- 105 FIG. 21 is a circuit diagram of a brightness compensating circuit which may be utilized in the embodiment of FIG. 18;
- 110 FIG. 22 is a block diagram of a code converter suitable for use in the character generator of FIG. 18;
- 115 FIG. 23 is a block diagram of a gated clock generator which may be employed to drive any of the character generators described herein;

FIG. 24 is a circuit diagram of a buffer amplifier which may be used to drive electromagnetic deflection yokes if the latter are used in place of electrostatic deflection plates to produce deflection fields; and

FIG. 25 is a circuit diagram of a deflection yoke driver for use with the circuit of FIG. 24.

Very generally the character generator of the invention comprises a plurality of magnetic cores 11 and means 12 for sequentially energizing such cores. (See FIG. 1.) A set of wires 13 is provided for producing information to generate a predetermined character. Respective wires in each set are wound on selected cores to produce, upon energization of the cores, pulses representative of incremental changes in beam deflection. Charging means 14 are provided for receiving the pulses produced in the wires upon energization of the cores. The charging means produce constant current output signals each of a predetermined duration corresponding to an increment of X- or Y-axis deflection. Storage means 16 and 17 are connected to the charging means to receive and accumulate the output signals supplied thereto from the charging means, thereby producing deflection voltages corresponding to the sum of the X- and Y-axis deflection increments, respectively. The storage means 16 and 17 are adapted for connection to the X-axis and Y-axis deflection means, 18 and 19, respectively, of a cathode-ray tube 21, to apply X-axis and Y-axis deflection voltages to the deflection plates.

GENERAL CONSTRUCTION AND OPERATION

Referring now particularly to FIG. 1, the general construction and operation of a character generator constructed in accordance with the invention will be described. Information for each character is generated in a respective one of a plurality of sets of wires 13. In the illustrated embodiment, there are three wires in each set, only one set being illustrated. One wire generates X-axis deflection voltage information in accordance with the manner in which it is wound or not wound on each of a series of magnetic cores 11. When the cores are closed rings, threading the wire through selected cores is sufficient to generate deflection information. A second wire generates the Y-axis deflection voltage information in the same manner. A third wire is utilized for some characters for which it is necessary to generate information indicating when the electron beam of the cathode-ray tube 21 is to be blanked during part of the character generating period; e.g. to prevent tracing the same segment of the character twice. Pulses representative of incremental changes in beam deflection, and blanking or unblanking of the electron beam, are produced by sequentially energizing the cores 11. If a wire is wound on a particular core, when the core is energized a pulse is produced in that wire, the polarity of the pulse depending upon the direction with which the wire is wound.

The sequential pulse generator 12 is utilized to energize the cores 11 sequentially. The circuitry for the sequential pulse generator may be of any suitable type, and specific types of circuits which may be utilized are shown in FIG. 6 and are described in detail subsequently. Generally, the sequential pulse generator may comprise a plurality of blocking oscillators, each connected to provide an output pulse for energizing one of the cores and for triggering the next succeeding blocking oscillator. Each magnetic core 11 may comprise the core of the blocking oscillator transformer, thus providing a substantial saving in the number of parts required. Where the timing of the pulse is particularly important, such as in the case of utilizing the illustrated apparatus as a stroke-type character generator, the sequential pulse generator may be timed with a suitable external clock oscillator, not illustrated in FIG. 1. The number of magnetic cores utilized determines the total number of available dots or strokes, and this may be varied to suit requirements. It has been found that a series of 18 to 20 cores provides a satisfactory number of dots or strokes, plus pulses indicative of starting and stopping each character as described below.

The particular set of wires for the production of the desired character which it represents is selected by character selection logic 22 which is coupled to one end of each set of wires. The character selection logic, the circuit of which is shown in FIG. 5 and is described fully below, receives information on the character to be selected from a computer, not shown. The end of each set of wires opposite the character selection logic is connected to gates 23, 24 and 26 for the X-axis deflection, Y-axis deflection and beam intensity functions, respectively. The gates 23, 24 and 26, as will be explained below, comprise OR gates which pass the outputs of a selected set of wires in response to appropriate operation of the character selection logic. The energizing pulses applied to each core by the sequential pulse generator 12 are so shaped as to result in the production of a single trigger pulse in each wire wound on that core for each core energization. The polarity of the trigger pulses depends upon the direction in which the wire is wound on the core.

The outputs of the X-axis deflection gate 23 and the Y-axis deflection gate 24 are applied to the charging means 14. The charging means operate in response to such trigger pulses to produce constant current output signals representative of increments of horizontal and vertical deflection. In the embodiment illustrated in FIG. 1, the charging means 14 include an X-axis pulse detector 27, a Y-axis pulse detector 28, a positive X-axis charging circuit 29, a negative X-axis charging circuit 31, a positive Y-axis charging circuit 32, and a negative Y-axis charging circuit 33. The X-axis pulse detector 27 separates trigger pulses applied to it from the gate 23 (such pulses being produced in the uppermost of the wires 13 and being representative of increments of X-axis deflection) and applies the positive pulses to the positive X-axis charging circuit 29 and applies the negative pulses to the negative X-axis charging circuit 31. Similarly, the Y-axis pulse detector 28 applies positive pulses to the positive Y-axis charging circuit 32 and negative pulses to the negative Y-axis charging circuit 33, depending upon the polarity of trigger pulses applied to the pulse detector 28 from the gate 24, such pulses being produced in the middle one of the wires 13. A circuit which may be employed for the charging means is shown in FIG. 5 and is described in detail hereinafter.

The output signals of the charging means 14 which represent increments of X-axis deflection, namely, the outputs of the positive X-axis charging circuit 29 and the negative X-axis charging circuit 31, are accumulated in a storage capacitor 16. Each incremental signal is a constant current pulse of a predetermined duration; i.e. an increment of charge. Similarly, the output of the charging means 14 representing increments of Y-axis deflection, namely the outputs of the positive Y-axis charging circuit 32 and the negative Y-axis charging circuit 33, are applied to a storage capacitor 17. A clamp circuit 35 operates at the end of the generation of each character to clamp the voltage on each storage capacitor 16, 17 to a starting or reference level before beginning the generation of the next character. The charge accumulated in each of the respective storage capacitors 16 and 17 is equal to the sum of the increments of charge applied thereto from the charging means. The voltage across each capacitor is proportional to the charge stored therein, and the capacitor voltages are applied across the X-axis and Y-axis deflection plates 18 and 19, respectively, in the cathode-ray tube 21. The cathode-ray tube 21 is also provided with a beam position deflection yoke 34 for positioning the traced characters at a desired region of the cathode-ray tube screen 36.

During the generation of some characters on the cathode-ray tube screen 36, certain sections of the character may have to remain unlighted or blanked. In the illustrated cathode-ray tube 21, the electron beam is produced by a cathode 37, and is directed to the screen 36 by suitable accelerating elements, not shown. A grid 38 is provided for controlling the intensity of the beam, and suitable changes in bias may be produced on the grid to blank or unblank the electron beam as desired. Such changes in grid bias are produced by an intensity circuit

39, coupled to the grid 38. As previously mentioned, the intensity circuit is controlled for blanking and unblanking the beam for those characters which so require it by means of a third wire in the set of wires 13. Trigger pulses produced in the third wire are applied through a gate 26 to the intensity circuit 39 to control operation thereof.

Where the character generator is operated as a dot-type generator, beam position is changed very quickly while blanked, and the beam is then unblanked while stationary to produce a dot on the screen 36 at a desired position. The characters are thus formed by a plurality of closely spaced dots. Under such operation, the intensity circuit 39 provides periodic unblank signals to the cathode-ray tube grid 38, which are spaced and which are of a length such that the beam is unblanked at the successive positions to which the beam is deflected. Where a blank space is necessary in a character, the pulses produced in the third wire are utilized in the intensity circuit to prevent an unblanking output from being applied to the grid 38, thus leaving the beam blanked in those positions. Details of circuitry for accomplishing the foregoing functions are shown in FIG. 7 and are described below.

Where the character generator of FIG. 1 is operated as a stroke-type generator, the intensity circuit 39 provides a continuous bias on the grid 38 to maintain the beam unblanked at all times except during the times that blank sections are required; e.g. to prevent tracing the same stroke twice. The output signals for stroke-type generation from the charging means 14 are constant currents which continue for the full period of each stroke. The accumulation of charges in the storage capacitors during each period results in ramp-type voltage signals which thereby cause the characters to be generated by a series of lines or strokes produced on the screen 36 of the cathode-ray tube 21. In the event a segment of a character is to be blanked, the appropriate pulses produced in the third wire of the set are applied through the gate 26 and are utilized by the intensity circuit to change the bias on the grid 38 to blank the cathode-ray tube beam. Details of circuitry for accomplishing the foregoing functions are shown in FIG. 16 and are described below.

Some characters, when properly proportioned, require larger or smaller increments in one axis than in the other axis, or a larger or smaller dimension in width or height than other characters. Those characters requiring a change in proportion from the standard character size are affected by the proportioning circuit 41, which is energized by the character selection logic circuit 22 at the same time the character is selected. The proportioning circuit is so constructed to enlarge or diminish the dimension of the character being generated along the X-axis or the Y-axis, depending upon which is appropriate, by the subtraction or addition of a suitable amount of capacitance to the storage provided by the capacitor 16 or 17. The proportioning circuit is also connected to the intensity circuit 39 for reasons explained below. Details of circuitry which may be used as the proportioning circuit are shown in FIG. 8 and FIG. 9 and are described below.

OPERATION AS DOT-TYPE GENERATOR

Referring now to FIGS. 2 and 3, an example of operation of the character generator of FIG. 1 as a dot-type character generator will be described in connection with the production of the capital letter G. FIG. 2 illustrates the appearance of the letter G on the cathode-ray tube screen, the numbers denoting the sequence in which the various dots are formed. The maximum number of dots with which a character may be formed corresponds to the number of cores 11 (FIG. 1) utilized for providing appropriate signals. In the illustration, 17 dot positions are shown, such as may be the case in a character generator using 18 cores, the last core providing a stop or reset pulse. Graph A of FIG. 3 indicates the available pulse times and Graphs B and C indicate the possible pulses utilized, and the polarity of pulses utilized, in the X-axis and Y-axis wires, respectively. As previously mentioned, the generation

of a pulse and its polarity is determined by the winding of the wires on the cores.

The dots 1 through 5 in FIG. 2 are formed by varying the Y-axis deflection voltage while holding the X-axis deflection voltage constant. This may be seen by comparison of Graphs D and E in FIG. 3. The step voltage characteristic is achieved by suitable short duration constant current output signals such as may be produced in a blocking oscillator, and by feeding such signals to the storage capacitors 16 and 17. The constant current output signals are fed to the storage capacitors for a fixed, predetermined time which is much shorter than the intervals between steps. The time is established by the blocking oscillator period and may, for example, be about 0.2 microsecond. Thus, the time required to move the beam from one dot position to the next is about 0.2 microsecond. The period for sequential energizations of the cores may be set at about 0.7 microsecond, and thus the beam may be left on for the remaining 0.5 microsecond to define a bright dot on the target screen. This is indicated by the Graph F, showing the production of successive intensity signals.

After illumination at the dot position 5 of FIG. 2, X-axis deflection begins to direct the beam to the positions 6, 7, 8 and 9. During the changes between the positions 6, 7 and 8, no change in Y-axis deflection voltage occurs, as may be observed from the graphs. Between positions 9 and 11, no change in X-axis deflection occurs, while the Y-axis deflection voltage decreases in stepwise manner through the application of negative constant current signals to the storage capacitor. The production of dots 10 and 11 is prevented by the generation of a blanking pulse in the third wire indicated in the Graph G of FIG. 3. This causes the unblank output from the intensity circuit as indicated by the Graph F to be absent during periods 10 and 11 so the beam remains blanked at positions 10 and 11. The beam is unblanked for position 12 and succeeding positions by the production of the next succeeding pulse in the third wire. At the dot 12 a slight inward excursion of the beam is produced by reducing the X-axis deflection voltage accordingly, indicated in the graphs. The remainder of the character is traced out as indicated by a comparison of the deflection voltages in the Graphs D and E, and the intensity signals in the Graph F.

Referring to FIG. 4, the illustration at A indicates the dot sequence followed in forming the character V when the increments of X-deflection and Y-deflection are equal. It may be seen that a pair of 45° slope lines results, the angle between the two sections of the V is 90°, and a disproportionate ratio of width to height of the character results. This is avoided by operation of the proportioning circuit 41 (FIG. 1) which will be described in detail below. Because of the operation of the proportioning circuit, the actual appearance of the letter on the screen of the cathode-ray tube is as in FIG. 4B, thus being properly proportioned.

In FIG. 5, circuitry is illustrated which may be employed in the character generator of the invention for operating it as a dot-type character generator. Only circuitry for the generation of the X-axis deflection voltage is illustrated, however, it is to be understood that the circuitry for generation of the Y-axis deflection voltage is similar. The character selection logic 22 includes a plurality of selection circuits, each comprising a pair of resistors 42 and a capacitor 43 connected to a common junction 45, to which one end of each wire in an associated set is also connected. The capacitor 43 is grounded and the resistors are connected to individual input points 44, to which the remaining portion, not illustrated, of the character selection logic 22 is connected.

The remaining unillustrated portion of the character selection logic 22 may be any suitable circuit which will bring both input points 44 to a positive potential (for example, +5 volts each) when that particular character is selected, and which will maintain either a zero voltage on both of the input points, or a positive voltage on one and a zero voltage on the other, when that particular character is not to be selected. The results of the foregoing described voltage conditions will be

set forth below. One particular satisfactory form of character selection logic may provide a character repertory of 64 characters, selected by six binary coded signals (six bits in parallel). As is known in the art, the six bits can be combined to produce 64 possible signals (2^6). Combining may be done in two stages, a first stage dividing the six bits into two groups of three each. Each group of three can be combined into eight possible combinations in the first combining stage. The 16 signals (two groups of eight) may be then combined to produce 64 unique signals, in the second combining stage, by means of 64 selection circuits, each consisting of a pair of resistors and a capacitor as described in connection with the resistors 42 and the capacitor 43. When the six binary signals of the character selection logic are set to select the character represented by the selection circuit having input points 44, one signal in each group of eight will be positive (the one connected to point 44 of the selected circuit), and the other seven in each group at 0. Thus, only one of the 64 selection circuits will have both inputs at positive potential, the other 63 having either both inputs at 0 volts or one input at a positive voltage and the other at 0 volts.

The opposite ends of the wires in each set are connected to the gates 23, 24 and 26, respectively. The gate 23 consists of a plurality of diodes 46 (64 diodes for 64 characters are used with character selection logic of the type described in the example, above), the outputs of the diodes being tied together and coupled to the X-axis pulse detector 27. The X-axis pulse detector 27 includes a transistor 47 having a collector connected through a resistor 48 to a source of potential. The collector is also connected through a capacitor 49 to ground. When a character is selected, its selection junction 45 rises to a positive potential; e.g. +5 volts. The particular one of the diodes 46 connected to the wire of the selected character is forward biased by the character selection logic 22 and causes the base of the transistor 47 to rise nearly to the positive potential of the selection circuit junction 45 to which it is connected. The transistor, under such conditions, is biased well into conduction. All of the other selection circuits are placed, by the character selection logic 22, in a condition such that the voltage at the particular selection junction is at either 0 or one-half that at the junction in the selected selection circuit; e.g. at 0 volt or +2.5 volts. At such voltages, the other diodes in the gate 23 are back biased; e.g. each diode has its cathode at nearly +5 volts and its anode at either 0 volt or +2.5 volts. With the transistor 47 biased well into conduction due to the biasing above described, pulses produced in the coding wire are passed by the associated diode. Such pulses may be positive or negative with respect to the bias level, depending upon the way the wire is wound on the cores. A pulse on a selected wire which occurs when a given core 11 is energized is positive if the wire is wound on that core in one sense, and negative if wound in the other sense. The pulses on the selected wire cause the transistor to produce pulses of corresponding polarity superimposed on its steady output resulting from the bias voltage. The emitter of the transistor 47 is connected through a resistor 52 and parallel capacitor 51 to a winding 53 which surrounds a portion of a magnetic core 54. The magnetic core 54 has a pair of output windings 56 and 57 which produce output pulses in response to pulses in the winding 53.

A satisfactory series of pulse configurations may be achieved by designing the sequential pulse generator 12 to produce square wave pulses of, for example, 0.6-microsecond duration. At the end of the 0.6-microsecond period, a sharp 0.2-microsecond overshoot pulse is utilized to trigger the next succeeding stage in the sequential pulse generator. A circuit for accomplishing this is illustrated in FIG. 6 and is described in detail subsequently in this specification. The resulting form of trigger pulses produced in the wires wound on the energized cores, such pulses being amplified by the transistor 47, are indicated adjacent the resistor 52 in FIG. 5. Depending upon the direction in which the wire is wound on a particular core, either the upper pulse or lower complementary pulse is produced upon the energizing of that core.

When the core 54 is energized by trigger pulses of such illustrated configuration, output pulses are produced in the windings 56 and 57 of a configuration as indicated in circles adjacent the core 54. A positive X-axis deflection pulse (the upper pulse adjacent resistor 52) applied to the winding 53 produces a pulse in the winding 56 having the configuration of the upper one of the two circled pulse forms. At the same time a pulse in the winding 57 is generated having the configuration of the lower of the two circled pulse forms shown. The opposite is true upon application of a negative X-axis deflection pulse (the lower pulse adjacent resistor 52) to the winding 53.

The winding 56 is connected across the base and emitter of a PNP transistor 58 through a capacitor 59. The transistor 58 is a pulse amplifier for driving the positive X-axis charging circuit 29. A biasing network comprised of resistors 61, 62 and 63 is provided, coupled to a suitable source 60 of positive potential, and is designed to bias the transistor 58 near cutoff. The winding 57 is connected to a pulse amplifier including a transistor 58a for driving the negative X-axis charging circuit 31, which is identical with that of the positive X-axis charging circuit 29. Since both pulse amplifiers are PNP transistors, they trigger only on negative pulses applied to their bases. Thus, each time the core 54 is pulsed, only one of the two output pulses in the respective windings 56 and 57 will be of a polarity to trigger the associated pulse amplifier transistor. The particular transistor which is triggered thereby depends on the polarity of the pulse in the winding 53.

The collector of the transistor 58 is grounded through a resistor 64, and provides an output pulse to the positive X-axis charging circuit 29, when a positive pulse is received by the gate 23 from a wire 13. The collector of the transistor 58a provides an output pulse to the charging circuit 31 when a negative pulse is received by the gate 23, in a similar manner.

In the charging circuit 29, the pulse from the transistor 58 is coupled through a capacitor 66 to the base of an NPN transistor 67. The base of the transistor 67 is grounded through a resistor 68 and a parallel connected diode 69. The transistor 67 is connected as a blocking oscillator, having a collector winding 71 with a parallel resistor 72 and having an emitter winding 73. A pair of resistors 74 and 76 connect a source 70 of positive potential to ground and the coil 73 is connected to the juncture between such resistors. The coil 71 is connected to a further source 75 of positive potential, and the coils 71 and 73 have a common core. Thus, the blocking oscillator is emitter coupled and provides a constant voltage output pulse in the secondary winding 77.

The secondary winding 77 is connected to provide a potential difference to the base-emitter circuit of a constant current NPN transistor 78. The transistor 78 has its base connected to one end of the winding 77, and its emitter connected through an emitter resistor 79 to the other end of the winding 77. The constant current output of the transistor 78 is coupled to the storage capacitor 16. The collector of the transistor 78 is connected to a source 80 of positive potential which is higher than the maximum deflection voltage to be produced across the X-axis deflection plates of the cathode-ray tube.

The first stage of the negative X-axis charging circuit 31 is identical with the first stage of the positive X-axis charging circuit 29 and similar parts are indicated with the same reference numeral and the subscript "a." The blocking oscillator of the negative X-axis charging circuit 31 operates to provide a constant voltage output signal by producing a signal of appropriate duration in the output winding 81 of the blocking oscillator. The output stage of the negative X-axis charging circuit includes a constant current transistor 82 having a current-determining emitter resistance consisting of a fixed resistor 83 and a variable resistor 84 connected to ground, and having its collector coupled to the storage capacitor 16. Thus, both the positive and negative incremental changes in the X-axis deflection voltage are determined by means of constant positive or negative currents fed to the capacitor for a fixed time predetermined by the time period of the blocking oscillator in the charging circuits.

Referring now to FIG. 6, one type of stage which may be incorporated in the sequential pulse generator 12 is illustrated. Such a pulse generator stage is capable of producing the square-wave-with-overshoot pulses previously described. It is to be understood, however, that the invention is not limited to the use of such a type of pulse generator or pulse configuration. Only one stage is shown in FIG. 6 and will be described, since it is to be understood that all stages are identical. A positive going signal from the next preceding stage or from a suitable start pulse circuit, not shown, is applied at the terminal 86. The terminal 86 is connected through a differentiating circuit including a capacitor 87 and a resistor 91. A diode 88 couples the differentiated signal to the base of an NPN transistor 89, the emitter of which is coupled through a resistor 92 to ground. The base of the transistor 89 is also coupled to ground through one winding 93, a feedback winding of a blocking oscillator transformer. The other winding 94 of the transformer is connected to the collector of the transistor and to a suitable source of positive potential 95. The winding 94 is also connected across a further winding 96 through a resistor 97 and a diode 98. The further winding 96 is wound on the associated core 11, upon which are also wound the wires 13. The collector of the transistor 89 is also connected to the next succeeding stage. The foregoing circuitry thereby operates as a base coupled blocking oscillator, providing output pulses to energize the associated core 11, and to also trigger the next succeeding stage.

When the transistor 89 is triggered into conduction by a positive input signal applied to its base, the collector current through the winding 94 increases, and the collector voltage drops. By the coupling of the transformer, the winding 93 drives the base further in the positive direction, causing a rapid regenerative decrease in the collector voltage until the collector voltage bottoms at substantially the emitter voltage of transistor 89. Current increases in the winding 94 thereafter, at a rate determined largely by the winding inductance and the supply voltage at terminal 95. When the transformer core becomes saturated (e.g. after 0.6 μ sec.), increasing current in winding 94 can no longer maintain a positive voltage on the base of transistor 89, and the regenerative "on" action stops. The base then returns toward 0 potential, which causes the collector current to be reduced, which drives the base further negative, so that collector current is rapidly cut off by a regenerative "off" action. The sudden interruption of collector current causes a positive going voltage step at the collector. Since the energy stored in the core of the transformer during the "on" interval of the blocking oscillator must be dissipated, the voltage at the collector overshoots, or wings to potential more positive than the terminal 95, and current is forced to flow through the diode 98, the winding 96 and the resistor 97. Part of the energy stored in the blocking oscillator transformer core thus is transferred to the core 11, magnetizing it and producing the desired information pulses in the wires 13, while another part is dissipated in the resistor 97. The time constant of the overshoot interval of the period is made small, by choosing a low value for resistor 97, so the pulses generated in wires 13 are short, e.g. about 0.1 μ sec.

During the "on" interval of the transistor 89, a signal is generated across resistor 92, which is proportional to emitter current. This signal is a ramp voltage superimposed on a pedestal, and is coupled to terminal 99. The signals at terminal 99 in the first and last blocking oscillators of the sequential pulse generator 12 are used in the intensity circuit 39, as will be explained hereafter, while the terminals 99 in the intervening stages are not used.

The positive going step in the collector voltage at the end of the "on" interval of the transistor 89 is coupled to the input trigger terminal 86 of the next stage, to initiate its action.

An intensity circuit, which may be utilized in the character generator of FIG. 1 when the character generator is operated as a dot-type character generator, is illustrated in FIG. 7. The circuit includes a flip-flop comprised of a pair of NPN transistors 101 and 102 connected in appropriate fashion by a

plurality of resistors, capacitors and diodes. The emitters of transistors 101, 102 are connected to a source of positive potential +V1, while the collectors are coupled to a more positive potential +V2. Ground potential can then be coupled to the bases through suitable bias resistors. An initiating signal from the emitter circuit (terminal 99) of the first stage in the sequential pulse generator 12 (FIG. 1) is applied to the unblank terminal 103 of the intensity circuit (FIG. 7). The initiating signal is applied to the base of one transistor 102 of the flip-flop through a capacitor 104 and a steering diode 106. When the first sequential pulse generator stage pulses, its emitter output signal sets the flip-flop to provide an output signal through a series resistor 107 to a buffer amplifier including an NPN transistor 108. The output signal provided through a resistor 109 from the transistor 108 is a square wave having substantial length, rather than a short pulse, and serves to enable or disable an unblank blocking oscillator which provides intermittent signals for unblanking the cathode-ray tube beam at appropriate times. The blocking oscillator is emitter coupled and includes an NPN transistor 111 having an emitter winding 112 and a collector winding 113. The emitter winding is connected to the resistor 109, and also to a source 105 of positive potential through a resistor 110. The collector winding 113 is connected to a source 105a of positive potential which is higher than the source 105. A series connected diode 115 and damping resistor 114 are connected in parallel with the winding 113.

In order to trigger the blocking oscillator (provided it is in the enabled condition) each time the cathode-ray tube beam has been stepped to a new position by the charging circuits 29, 31, 32 or 33, (FIG. 1), output signals from the charging circuits are connected through an OR gate consisting of four diodes 116. The output signals are obtained from the emitter circuits of the charging circuit blocking oscillators; e.g. terminals 75, 85 in FIG. 5. The diodes 116 are slightly back biased by a source 117 of positive potential connected to their cathodes through the parallel combination of a resistor 118 and a capacitor 119. At each timing interval (see Graph A, FIG. 3) a pulse will be passed by the OR gate diodes 116, since a pulse sufficient to overcome the back bias is present in at least one of the four charging circuit outputs. This pulse is applied to the base of the transistor 111 through a resistor 121 and parallel capacitor 122. The pulse applied to the base of the transistor is a positive going pulse and triggers the blocking oscillator (providing it is in the enabled condition). A pulse is therefore produced in the output winding 124 of the blocking oscillator.

The pulse produced in the output winding 124 is coupled across the emitter and base of a PNP output transistor 126 through a resistor 127. The output of the transistor 126 is developed, from a source 125 of positive potential tied to the emitter, across a load resistor 128 in the collector circuit and applied to the cathode-ray tube grid. The circuitry may be designed such that the blocking oscillator produces a negative going rectangular pulse nominally about 0.3 microsecond in width and 9 volts in magnitude at the collector of the transistor 111, with a positive overshoot lasting about 0.3 μ sec. following its trailing edge. A wave of the same shape, but inverted and about one-quarter of the magnitude (assuming a turns ratio of nine turns on the collector winding 113 and two turns on the output winding 124) appears at the upper end of the output winding and couples to the base of the output transistor 126. The output transistor is normally off (at 0 bias) and is turned farther off by the positive rectangular pulse (during the transition time between spot positions). During the overshoot time of the blocking oscillator, the output transistor 126 clips and amplifies and inverts the negative overshoot, producing a short positive unblank pulse at its collector. This pulse is applied to the grid of the cathode-ray tube for unblanking the beam.

The circuit of FIG. 7 represents a simple embodiment of the intensity circuit 39 which can be used in the character generator of FIG. 1. By the use of alternative intensity circuits in

which the blocking oscillator is replaced by a combination of two blocking oscillators in cascade, the delay period and unblank period can be controlled independently. The delay period to allow for transition of the spot can be reduced to 0.2 μ sec., or any other desired interval by proper design and adjustment of the first blocking oscillator. The unblank interval can be increased to 0.5 μ sec., or any other desired interval, by proper design and adjustment of the second blocking oscillator, as is well known in the art.

The flip-flop 101-102 is placed in the reset or disabling condition, as described below, when certain dots are not to appear on the cathode-ray tube screen. (The reset condition corresponds to conduction of transistor 101). When the flip-flop is disabled, the buffer amplifier transistor 108 conducts heavily from the positive voltage source at its collector through the resistor 109 and the further resistor 110 to the lower potential source 105 to which the resistor 110 is connected. The current through the resistor 110 causes the blocking oscillator transistor 111 emitter to rise to a substantially more positive potential than its base. Hence, triggering of the blocking oscillator by pulses from the diodes 116 is prevented.

In the illustrated circuit, the flip-flop 101,102 is controlled by blank and unblank pulses produced in the third line or wire. Such pulses are applied through the OR gate 26 to a two-stage amplifier. The two-stage amplifier is comprised of a pair of NPN transistors 131 and 132 connected by suitable biasing resistors and capacitors respectively in an emitter follower configuration and a grounded emitter configuration. Such pulses are applied to the flip-flop comprising the transistors 101 and 102 through a capacitor 133, and also through a capacitor 136. The first pulse (see FIG. 3 G) operates the flip-flop to the reset or disabling condition, causing the buffer amplifier to disable the blocking oscillator. The second pulse sets the flip-flop again to a condition wherein the buffer-amplifier enables the blocking oscillator. In addition, an unblank inhibit pulse is applied to a terminal 138 by the last stage of the sequential pulse generator 12 (FIG. 1). This pulse is applied to the flip-flop through a capacitor 139 and operates the flip-flop to the reset or disabling condition when the generation of a character is completed. Thus, the cathode-ray tube beam is blanked until such time as generation of a new character begins and a pulse is applied to the terminal 103.

By utilizing the flip-flop consisting of the transistors 101 and 102, it is possible to generate many types of characters without the necessity of a third wire being threaded through the cores 11. Thus, if no portions of a character are to be blanked or retraced, it is unnecessary to inhibit the output of the blocking oscillator. If the character shape requires a blanked portion or a retraced portion, the third wire need only be threaded through two cores for each blanked segment, rather than threaded to provide blanking pulses for each beam position. Thus, the first pulse produced in the third wire resets the flip-flop (which is initially set upon the production of a pulse in the first core 11) and the second pulse produced sets the flip-flop once again to a condition for enabling the blocking oscillator.

The unblank pulse applied by the first sequential pulse generator to terminal 103 and unblank inhibit pulse applied by the last sequential pulse generator to terminal 138 are not both required for operation of the character generator. If the inhibit pulse at terminal 138 is omitted, it is necessary to thread the third wire 13 to generate an additional pulse to blank the cathode-ray tube beam after the last desired dot is produced. Conversely, the unblank pulse to terminal 103 can be omitted if the third wire 13 is threaded to generate an additional pulse before the first desired dot is produced.

As an alternative intensity control method, the third wire 13 may be threaded to produce positive pulses when it is desired to unblank the beam and negative pulses when it is desired to blank the beam. The intensity circuit in that event is accordingly modified to include a pulse detector and separator like transistor 47 and core 54 (FIG. 5) with its windings 53, 56, 57. The separated pulses from the two output windings of

the core are then used respectively to set and reset the intensity flip-flop via separate steering diodes.

As a further alternative, the intensity circuit 39 may be modified to operate without the flip-flop and without the OR gate comprised of the diodes 116. Under such circumstances, the third wire for each character is threaded through a core for each dot to be brightened. The pulses produced in the third wire are then coupled, by suitable amplification, directly to the input of the blocking oscillator.

FIGS. 8 and 9 illustrate enlarging and diminishing circuits, respectively, which may be utilized as the proportioning circuit 41 in FIG. 1. Two enlarging circuits and two diminishing circuits, one for each for each axis, may be provided. Satisfactory operation is possible with only one proportioning circuit per character generator, however. In the enlarging circuit of FIG. 8, a diode 141 (FIG. 8) is used for each character to be enlarged, and is connected to the input resistor junction 45 for that particular character in the character selection logic 22. The plurality of diodes 141 are arranged to form an OR gate and function in a manner similar to the OR gates for the charging means and for the intensity circuit. If a character is selected which requires enlargement, a signal (e.g. +5 v.) is passed by the associated one of the diodes 141 to the base of a first of a pair of NPN transistors 142 and 143 having a common emitter resistor 144 connected to ground. The base of the first transistor 142 is also connected to ground through a resistor 146, and the base of the second transistor 143 is connected to ground through a resistor 147. The base of the second transistor 143 is also connected through a resistor 148 to a source of positive potential. The resistors 147, 148 form a voltage divider which bias the base of the second transistor 143 to a suitable positive potential; e.g. +2.5 volts. The collector of the first transistor 142 is also connected to a source of positive potential. Without any positive signal being passed by any of the diodes 141, the first transistor 142 is biased off and the second transistor 143 is biased on.

A capacitor 149 is connected between the collector of the second transistor 143 and the storage capacitor 16 or 17 for the axis to be enlarged. The capacitor 149 is normally (i.e. when the second transistor 143 is biased on) in the system and effectively in parallel with one of the capacitors 16, 17; however, when a sufficiently positive signal; e.g. +5 v., is passed by one of the diodes 141, the first transistor 142 is rendered conductive, cutting off the second transistor 143 and, in effect, removing the capacitor 149 from the system. Accordingly, less storage capacity is present, producing an enlargement of the character.

Referring now to the diminishing circuit shown in FIG. 9, an OR gate comprised of a plurality of diodes 151 receives signals from the input resistor junctions 45 for those characters to be diminished, which input junctions are in the character selection logic 22. The base of an NPN transistor 152 is connected to the diodes 151 through a resistor 153. The base of the transistor 152 is also connected through a resistor 154 to a source of negative potential, and the emitter is grounded. Accordingly, the transistor is normally biased to an off condition. In the presence of a sufficiently positive signal passed by one of the diodes 151, however, the transistor 152 is rendered conductive. A capacitor 156 is connected between the collector of the transistor 152 and the storage capacitor 16 or 17 associated with the particular axis to be diminished (normally the X-axis). Accordingly, when the transistor 152 is rendered conductive, the capacitor 156 is added to the system effectively in parallel with one of the capacitors 16, 17, resulting in a diminishing of the character on the associated axis.

The theory of operation of the enlarging and diminishing circuits is explained by the physical laws of electrical charge. Charge (in coulombs) is equal to the product of time (in seconds) and current (in amperes). If current varies during the interval of time in which it flows, charge is the integral of current over the time interval; i.e.

$$Q = \int_{t_1}^{t_2} idt$$

Each time one of the charging circuits 29, 31, 32, 33 is triggered by a pulse from a wire 13, it provides a predetermined pulse of current extending over a fixed time interval, i.e. a predetermined increment of charge, to the associated storage capacitor 16 or 17. Where the output stage of each charging circuit is referred to as a constant current generator in the description of the dot generator, this signifies only that it provides a current which is independent of the voltage at its output terminal. In practice, the current varies during the brief interval of each charging pulse, rising from 0 to a maximum, continuing at the maximum for a time, and then falling to zero. The increment of charge in each such pulse is thus properly determined as the integral of current over the time interval, but is nevertheless a fixed increment of charge.

The voltage V (in volts) across the capacitor is proportional to the charge Q (in coulombs) stored therein, and inversely proportional to the capacitance C (in farads).

$$V = Q/C$$

It follows that the addition of a fixed increment of charge, ΔQ , produces a fixed increment of change in voltage, ΔV , if capacitance C is fixed.

$\Delta V = \Delta Q/C$ The reciprocal of capacitance, $1/C$, is therefore a proportionality factor relating ΔV to ΔQ . If C is reduced, then a given ΔQ produces a larger ΔV ; conversely if C is increased,

a given ΔQ produces a smaller ΔV . The enlarging and diminishing circuits change the value of capacitance and thus result in greater or lesser increments of voltage in response to each fixed increment of charge.

In between generation of successive characters, the X-axis storage capacitor 16 and the Y-axis storage capacitor 17 are clamped to a fixed starting potential by means of the clamp circuit 35. In FIG. 10, circuitry which may be utilized as the clamp circuit 35 is illustrated. An NPN transistor 157 has its collector connected to the ungrounded side of the X-axis storage capacitor 16 and has its emitter connected to a source of positive potential at a reference level. Similarly, an NPN transistor 158 has its collector connected to the ungrounded end of the Y-axis storage capacitor 17 and has its emitter connected to a source of positive voltage at the reference potential. A flip-flop, described below, is used to switch the transistors 157 and 158 into a conductive state between generation of characters to clamp the capacitor voltages at the reference levels. When a character is to be generated, the transistors 157 and 158 are switched to a nonconductive state. Biasing resistors 159 and 161 form a biasing network for the base of the transistor 157 by connection to a source of potential which is substantially higher than the emitter source. Similarly, biasing resistors 162 and 163 are provided for the base of the transistor 158, and are connected to a source of potential which is substantially higher than the emitter source.

The flip-flop which controls the conduction of the two transistors 157 and 158 includes a pair of NPN transistors 164 and 166. The emitters of the transistors 164 and 166 are grounded and the bases are connected to a source of negative potential respectively through resistors 171 and 168. The collectors of the transistors are cross coupled to the bases of the transistors by resistors 167 and 169. The collectors of the transistors 164 and 166 are also connected through resistors 173 and 174 to a source of positive potential which is lower than the potential at the high end of the resistors 162 and 159.

In the clamped condition, the transistors 157 and 158 are biased into conduction due to the condition of the flip-flop in which the transistor 166 is conductive and the transistor 164 is cut off. The pulse for unclamping the storage capacitors 16 and 17 is obtained from a suitable point; e.g. terminal 99, in the first stage of the sequential pulse generator 12 and is applied to a terminal 176. The pulse is positive and is applied through a resistor 177 and a diode 178 to the base of the transistor 164. This renders the transistor 164 conductive, thereby dropping the voltage on the bases of the transistors 157 and 158 to a point where the transistors are cut off. At the same time, the base voltage on the transistor 166 goes to a negative value to cut off that transistor and hold the transistor

164 in the conductive condition. Upon completion of the generation of a character, a suitable positive going pulse is obtained from the terminal 99 in the last stage of the sequential pulse generator 12 and is applied to the terminal 179. This pulse is applied through a delay circuit including a series resistor 181 and filter capacitor 182, and through a further resistor 183 and a diode 184 to the base of the transistor 166. The potential on the base of the transistor 166 is raised by the pulse sufficiently to cause that transistor to become conductive, cutting off the transistor 164 and turning on the transistors 157 and 158 to clamp the storage capacitors 16 and 17.

In one embodiment of the dot-type character generator described in FIGS. 1-10 of this invention, the following power supply voltages are used successfully:

20	+V2	+18 volts DC
	+V1	+ 6 volts DC
	-V	- 6 volts DC

Other voltages can be used, as is well known in the art, if the various circuits are designed accordingly.

OPERATION AS STROKE-TYPE GENERATOR

As previously indicated, the character generator of FIG. 1 may be operated as a stroke-type character generator rather than as a dot-type character generator as described above. A stroke-type character generator generates characters by utilizing a series of strokes, and circuitry may be designed to provide eight stroke directions as shown in FIG. 11. These available strokes may be used in producing characters as in the example given for the letter C in FIG. 12. It may be seen from FIG. 12 that in generating the letter C, the first three strokes are blanked (Note, for purposes of illustration the first three strokes are shown displaced slightly downward), the fourth stroke position is blanked but the beam is stationary and then strokes 5 through 12 are unblanked, only 12 strokes being required to complete the character. Following the 12th stroke, the beam is once again blanked.

Referring now particularly to FIG. 13, the wave form characteristics required for generating the character C illustrated in FIG. 12 may be seen. Assuming 18 cores and therefore 18 available pulse times, as indicated in Graph A, the X-axis wire pulse pattern and the Y-axis wire pulse pattern are produced as in Graphs B and C, respectively, by appropriate winding of the X-axis and Y-axis wires on the selected cores. The charging circuits 29, 31, 32 and 33, which are described in greater detail below, produce a continuous current output signal for a period of time which is equal to the time period between pulses. Thus, a ramp-type change in deflection voltage is produced, as shown in Graph D or E of FIG. 13, to sweep the beam in a desired direction, rather than a step-type movement of the beam as was the case in the dot-type character generator described previously. In beginning generation of character C, the Y-axis deflection voltage is held constant at the reference potential while a positive going X-axis ramp is produced by a positive pulse on the X-axis wire at the first pulse time. At the third pulse time, a positive pulse in the Y-axis wire produces a positive going ramp characteristic in the Y-axis deflection voltage to move the beam upward to the upper right-hand end of the third stroke (FIG. 12). At the fourth pulse time, positive pulses terminate the positive going ramps in both X and Y. At the fifth pulse time, negative pulses in both the X-axis and Y-axis wires initiate negative going ramps in both X-axis and Y-axis deflection voltages, causing a retrace of the beam. At the sixth pulse position, a negative pulse in the Y-axis wire levels off the Y-axis deflection voltage while the X-axis deflection voltage continues to move the beam to the left. The following pulses in both the X-axis and Y-axis wires are produced at appropriate times to cause the beam to trace out the pattern illustrated in FIG. 12.

It will be observed that pulses are produced in the appropriate wire 13 only when the slope, which may be negative, zero, or positive, is to be changed. The winding of the wires 13 is thus simplified, since fewer pulses are required. As an additional advantage, the portions of characters which are straight line segments two, three, or four unit strokes in length are made without any discontinuity or variation in intensity, since both X- and Y-ramps continue uninterrupted through the intermediate points, and no pulses are produced in the wires 13 which could couple noise signals into the deflection circuits during the sweeps of extended length.

The unit stroke length in a given axis is defined as the distance the beam of the cathode-ray tube is deflected in one time period of the sequential pulse generator. An increment of deflection in a given axis is defined as the distance the beam moves between successive changes in its rate of motion; in the embodiment of FIG. 13 an increment is the distance the beam moves between successive pulses on the controlling wire 13. An increment of deflection thus may be any integral number of unit strokes in length, as required by the character. Increments of deflection in one axis may or may not commence and end at the same time as increments in the other axis.

In order to unblank the beam at the beginning of the fifth stroke and to continue the beam in an unblanked condition, through the 12th stroke, the third or intensity wire is wound to produce pulses as illustrated in Graph F of FIG. 13. This causes the intensity circuit to produce a voltage as illustrated in Graph G of FIG. 13 for holding the beam in an unblanked position in strokes five through 12 and for blanking the beam subsequent to the 12th stroke. Suitable circuitry for accomplishing this is described below.

By utilizing two lines or wires per character, ramp-type deflection voltages may be generated to produce eight different stroke directions as illustrated in FIG. 11. For example, stroke number one is produced by holding the Y-axis deflection voltage constant and producing a ramp type X-axis deflection voltage. As a further example, stroke number 8 (FIG. 11) is produced by means of a positive going ramp X-axis deflection voltage and a negative going ramp Y-axis deflection voltage. By starting the first stroke from an appropriate position, combining these various strokes in sequence, and by blanking the electron beam, where necessary, a variety of characters may be generated.

In a stroke-type character generator, good character definition generally requires that the beginnings and ends of the strokes be precisely timed. Accordingly, it is desirable that the sequential pulse generator 12, when the character generator is constructed for stroke-type character generation, be timed by an accurate series of clock pulses. Such pulses may be produced by any suitable commercially available clock pulse generator, and may be utilized to actuate the successive stages of the sequential pulse generator 12 so that each of the cores 11 is energized at precisely the correct time. One form of circuitry for accomplishing this and which may be utilized in the sequential pulse generator 12 is illustrated in FIG. 14.

Two successive stages of the sequential pulse generator are illustrated in FIG. 14, and the remaining stages may be similarly constructed. Only the first of the stages is described hereinafter, similar parts on the second stage being indicated with the same reference numeral and the superscript ('). Each stage comprises an emitter coupled blocking oscillator including an NPN transistor 186. The emitter of the transistor 186 is connected through the blocking oscillator transformer winding 187 and an emitter load resistor 192 to ground. Resistor 191 couples the junction of resistor 192 and winding 187 to one end of a storage capacitor 193. The other end of capacitor 193 is connected to ground. Resistor 191 and capacitor 193 together are a steering circuit coupling the first blocking oscillator to the second blocking oscillator. The other winding 194 of the blocking oscillator transformer is series connected between the collector of the transistor 186 and a source of positive potential. A transient suppressing diode 196 is connected in parallel with the winding 194. The core of the blocking oscillator transformer comprises one of the magnetic

cores 11 upon which the character generating wires are wound. Base bias for the transistor 186 is provided by connecting the base through a resistor 197 to a source of negative potential. The base is clamped so it can be only slightly negative with respect to ground, by a diode 198 connecting the base to ground.

A capacitor 201 and a diode 202 couple a clock pulse input terminal 199 to the base of the transistor 186. The anode of the diode 202 is biased by a resistor 211 connected to a negative source 189 and is connected to an input enabling terminal 206 by a resistor 209. When the enabling terminal 206 is at zero voltage, the diode 202 is back biased, but when the terminal 206 is sufficiently positive, the diode 202 is forward biased.

A sequence of operations is started by applying a positive START signal to enabling terminal 206, thereby forward biasing diode 202. Positive going clock pulses are periodically applied at the clock pulse input 199, and the first clock pulse after receipt of the START signal is passed by capacitor 201 and diode 202 to the base of the transistor 186 to trigger the first blocking oscillator. A positive going pulse is generated at the emitter load resistor 192, and is delayed and elongated by resistor 191 and capacitor 193. The delayed pulse at capacitor 193 is coupled to the enabling terminal of the next stage, which is identical with the described stage.

The delayed and elongated positive pulse at capacitor 193 increases the voltage at the junction of resistors 209' and 211' sufficiently that the coupling diode 202' is forward biased, and the next clock pulse is able to trigger the second blocking oscillator. The enabling pulse from the first blocking oscillator is delayed sufficiently by resistor 191 and capacitor 193 that the second blocking oscillator cannot be triggered by the same clock pulse which triggered the first stage. The positive signal stored in capacitor 193 also prevents retriggering of the first blocking oscillator at the time of the second clock pulse after a START signal, by holding the emitter of transistor 186 substantially more positive than the base until after the second clock pulse has occurred. In the case of the first stage only, the inhibiting effect of the positive emitter voltage is unnecessary as the START signal at terminal 206 is removed before the second clock pulse arrives.

In the case of any stage except the first, the positive voltage applied to the emitter of a stage which has just triggered, by the capacitor 193' associated therewith, assists in preventing double triggering of the stage, in the event that the capacitor 193 in the preceding stage has not completely discharged during the previous clock pulse period.

In order to produce the ramp voltage for sweeping the cathode-ray tube beam as previously described, the charging circuits may take the form illustrated in FIG. 15. The particular circuit illustrated therein is for producing a positive charge, however, an appropriate negative charge may also be produced by similar circuitry as will be apparent to those skilled in the art. The circuit includes a constant current generator incorporating an NPN transistor 212 having its emitter coupled to ground through a resistor 213 and having its collector coupled to source of positive potential V2 through a resistor 214. The collector is also coupled through a variable resistor 216 and fixed resistor 217 to the emitter of a PNP transistor 218. The base of the transistor 218 is connected to a source of positive potential V1, lower than the potential at V2, and the collector is connected to the storage capacitor 16 or 17 to provide the appropriate charge in deflection voltage. Input signals are applied to the current generator by means of suitable on-off flip-flop 220, and the flip-flop and constant current generator comprise the charging circuit (29 or 32 in FIG. 1).

The pulse detector 27 or 28 in FIG. 1 which precedes the charging circuit may be of the same circuitry as shown and described in FIG. 5. The flip-flop 220 which precedes each current generator may be any suitable bistable circuit arranged to produce an output every other time a pulse is received. Thus, in the case of FIG. 15, receipt of a pulse of the

proper polarity by the flip-flop 220 changes its state and brings the base of the transistor 212 to near zero. This cuts the transistor 212 off. Since the base voltage of the transistor 218 is fixed at a positive potential its emitter is returned to higher positive potential through resistors 217, 216 and 214 and its collector current is nearly constant; the transistor 218 operates as a constant current generator, charging the storage capacitor. When the flip-flop changes state upon receipt of a second pulse of the same polarity, the potential on the base of the transistor 212 is raised to a positive value, rendering the transistor 212 conductive and thereby dropping the voltage on the emitter of the transistor 218. This cuts off the transistor 218 to prevent further charging of the storage capacitor. The flip-flop 220 for positive charging in one axis will change state each time a positive pulse is received by the pulse detector circuit of that axis from the associated wire 13. The corresponding flip-flop for negative charging changes state each time the same pulse detector receives a negative pulse from the same wire 13. The pulse detector, as previously described, provides output pulses at one or the other of its output terminals each time its magnetic core is energized.

One form of intensity circuit 39 which may be used in the character generator of FIG. 1 when such is operated as a stroke type character generator is illustrated in FIG. 16. The intensity circuit operates to both blank the beam when required, and to vary the beam intensity to maintain uniform brightness in character segments even though the beam deflection speed may vary. The presence of sufficiently positive selection voltage in one of the intensity wires connected to the gate 26 makes the associated diode conductive and raises the base of an NPN transistor 221 to render the transistor conductive. A load resistor 222 which couples the output of the gate 26 to ground insures sufficient forward current in the conductive diode to provide low impedance to the pulses from the wire 13. The collector of the transistor 221 is connected through a resistor 223 to a source 224 of positive potential, and is also connected through a decoupling capacitor 226 to ground. The emitter of the transistor 221 develops an output signal across a load resistor 227 connected to ground. A voltage supply source 228 of positive potential is connected to the resistor 227 by a resistor 229 to bias the emitter slightly above ground potential when no positive signal is applied via any intensity wire, thus rejecting small noise pulses on the wires 13. When the positive signal is applied, the transistor 221 operates as an emitter follower and amplifies pulses produced in the selected character's intensity wire in accordance with the manner in which such wire is wound upon selected cores.

The output of the emitter follower transistor 221 is applied through a coupling capacitor 231 to the base of an NPN transistor 232. The transistor 232 is connected as a pulse amplifier, having a biasing resistor 233 and a load resistor 234 connecting its base and collector, respectively, to a source 236 of positive potential. A resistor 237 connects the base of the transistor 232 to ground, and the emitter of the transistor 232 is coupled directly to ground. Pulses amplified in the emitter follower transistor 221 are further amplified in the pulse amplifier transistor 232 to provide an output at the collector of the latter transistor.

The output of the pulse amplifier transistor 232 is applied to each of the two inputs 238 and 239 of a flip-flop 241. The flip-flop 241 may be any suitable high-speed gated flip-flop capable of being switched to complementary or opposite stable states upon successive pulses applied to the inputs 238 and 239. The flip-flop is also provided with inputs 242 and 243 capable of disabling and enabling, respectively, the flip-flop. A signal from the last stage in the sequential pulse generator may be applied to the input 242 in order to disable the flip-flop 241 upon completion of each character generation. The flip-flop includes outputs 244 and 246, and provides signals therat in response to switching of the flip-flop by appropriate pulses applied to the inputs 238 and 239. A flip-flop having a capability suitable for use as the flip-flop 241 is manufactured by Fairchild Semiconductor under the designation DTuL 950.

Before the beginning of character generation, a pulse from an external start signal used to initiate the sequential pulse generator may be applied to the input 242. This insures that the voltage at the output 246 is at zero and the voltage at the output 244 is at a positive potential. The first output is open-circuited. When the voltage at the output 244 is a positive voltage, the cathode-ray tube beam is turned off or blanked, as will be described below. Upon receipt of a pulse from the pulse amplifier transistor 232, the flip-flop 241 changes state, causing unblanking of the cathode-ray tube beam as described below. The next succeeding pulse produced by the pulse amplifier transistor 232 causes the flip-flop 241 to once again change state and blank the cathode-ray tube beam. Alternatively, the start signal may be applied at the input 243 to set the flip-flop to an unblanked condition, and the deflection and intensity wires 13 may be threaded in a manner consistent with this mode of operation. In the illustrated version, however, the output 244 of the flip-flop 241 is initially at a positive or blanking voltage and will drop to zero only when the cathode-ray tube beam is tracing some portion of the path which is to be seen.

The output 244 of the flip-flop 241 is employed to control the blanking and unblanking of the cathode-ray tube. In this connection, the output 244 is connected by means of a lead extending through a resistor 247 to the base of an NPN transistor 248. The emitter of the transistor 248 is coupled directly to ground, and the collector of the transistor 248 is coupled to the base of a transistor 249. The base of the transistor 249 is prevented from going below ground by diode 251. The collector of the transistor 249 is connected to a source 252 of positive potential, and the emitter of the transistor 249 is connected through a grid bias load resistor 253 to ground and to the grid of the cathode-ray tube for applying bias voltage thereto from the source 252. In the presence of a blanking or positive voltage at the output 244, the transistor 248 is rendered conductive and the base of the transistor 249 is therefore shorted to ground. This renders the transistor 249 substantially nonconductive, providing no output voltage to the grid of the cathode-ray tube. In the absence of an output signal at the output 244 of the flip-flop 241, the transistor 248 is substantially cut off. Under this condition, as will be explained, the transistor 249 becomes conductive, applying a positive signal to the cathode-ray tube grid to unblank the beam.

As may be seen in FIG. 11, the length of the angular strokes is greater than the length of the axial strokes by a factor of the square root of 2. Since the time available for tracing a stroke is the same for angular or axial strokes, the beam deflection speed is greater during tracing of the angular strokes. In order to compensate the brightness of the cathode-ray tube beam for differences in speed during the axial strokes as compared to the angular strokes, signals in the charging circuits are sampled to determine the type of stroke being made. The particular signals may be obtained from any suitable place in the charging circuits, one satisfactory point being at the output of the flip-flop in the charging circuit (e.g. flip-flop 220 in FIG. 15). The outputs of the flip-flops in the charging circuits are applied to the bases of four NPN transistors 254, 256, 257 and 258, respectively. The emitters of the transistors are directly connected to ground, and the collectors of the transistors are coupled in pairs according to the X-axis deflection and Y-axis deflection inputs. Thus, the collectors of the transistors 254 and 256 are connected through a resistor 259 to a point 261. Similarly, the collectors of the transistors 257 and 258 are connected through a resistor 262 to the point 261. Each pair of transistors forms a NOR gate such that if either transistor in the pair is conductive due to a positive voltage at its base, indicating a component along that axis (X or Y, respectively), the juncture of their collectors is at ground. If there is no positive or negative component in a particular stroke for the associated axis, so that the bases of both transistors in the pair are at zero, the collectors are open-circuited.

The point 261 is connected through a variable resistor 263 to a source of positive potential 267. A part of the signal

developed across variable resistor 263 is coupled through a further resistor 264 to the base of a PNP transistor 266. The two resistors 259 and 262, together with the potentiometer 263, comprise a combining network which nonlinearly adds the collector signals of the transistor pairs representing the X and Y AXES. Reference voltage is supplied to the network from the source 267 of positive potential, such source also being connected to the emitter of the transistor 266. Thus, the signal produced across the potentiometer 263 in the event one or more of the transistors 254, 256, 257 and 258 is conductive, is a negative going signal with the potential of the source 267 as a reference. Proper compensation for different writing speeds is achieved by suitable selection of the values of the resistors 259 and 262, the potentiometer 263 and the reference voltage 267. Thus, where the reference voltage is at 9 volts, where the total resistance of the potentiometer 263 is 100 ohms, and where each of the resistors 259 and 262 equal 150 ohms, a stroke having either an X-axis or a Y-axis component but not both results in the point 261 dropping to about 3.6 volts below the reference level. Where both X-axis and Y-axis components (as in a 45° stroke) are present, one transistor in each pair will conduct and the point 261 will be pulled 5.1 volts below the 9-volt reference level. Since the 5.1-volt signal is 1.4 times as great as the 3.6-volt signal, the 1.4 times greater length of the 45° stroke is compensated for by an appropriate-ly greater unblank signal amplitude.

The base of the transistor 266 is connected through a resistor 268 to a potentiometer 269. The potentiometer 269 is connected between a source 271 of positive potential and ground. The source 271 is more positive than the source 267. By appropriate adjustment of the tap of the potentiometer 269, a voltage is applied to the base of transistor 266 which determines its operation when no signal is applied from point 261. The collector of the transistor 266 is coupled through a resistor 274 to a source 276 of negative potential, and is also coupled through a resistor 277 to the base of the transistor 249. A feedback path from the emitter of the transistor 249 to the base of the transistor 266 is provided through a pair of series resistors 278 and 279. Thus, the transistors 266 and 249 are connected to form a linear feedback amplifier. The base of the transistor 266 is biased through the resistor 268 with a DC signal, and receives a compensating signal for 45° strokes from the point 261 via the potentiometer 263 and the resistor 264. Feedback reaches the base of the transistor 266 through the resistors 278 and 279. The transistor 266 is connected as an inverting amplifier and its collector operates in the range from zero volts to the potential at the source 267 (+9 volts for example).

The transistor 249 is an emitter follower providing a low-impedance output. As previously mentioned, the output of the transistor 249 is substantially zero in the presence of a blank signal at the output 244 of the flip-flop 241. In the absence of a blank signal, the output of the transistor 249 is proportional to the sum of the two input voltages at the base of the transistor 266. When deflection only along a single axis is taking place, the output is of the amplitude of the pedestal level 293 as shown by the wave form 273. When a 45° stroke is generated, the amplitude of the output of the transistor 249 increases appropriately, as indicated by the level 294 in the wave form 273. During generation of one character, the output of the transistor 249 may change between zero level 292, the pedestal level 293, and the level 294 for 45° stroke compensation, all indicated on the wave form 273. The minimum time at which the output of the transistor 249 remains at one of the three amplitudes is the time of displacement of the beam through one stroke. The adjustment of the potentiometer 269 determines the pedestal level 293, and the adjustment of potentiometer 263 determines the level 294.

Variation in writing speed also results from operation of the character proportioning circuit 41 in FIG. 1, due to the changes in stroke length which result from operation of the proportioning circuit. Such changes in speed are compensated for by varying the attenuation of the feedback network in the

intensity circuit. Two input terminals 280 and 281 are provided to which signals indicating enlargement of the X-axis or Y-axis, respectively, are applied. The terminals are connected to appropriate places in the proportioning circuit such that they are at zero potential when no enlargement along the associated axis is to take place, and are at a positive potential when enlargement along the associated axis is to take place.

The intensity circuit 39 includes a series arrangement of a resistor 282, a pair of diodes 283, and a resistor 284, all connected in series and in stated order between a source 286 of positive potential and a source 287 of negative potential. The terminal 280 is connected to the juncture between the resistor 282 and the first diode 283. The juncture between the second diode 283 and the resistor 284 is connected to the base of an NPN transistor 288. The emitter of the transistor 288 is directly coupled to ground, and the collector is coupled through a variable resistor 289 and a fixed resistor 290 to the juncture between the resistors 278 and 279 in the feedback network.

An identical arrangement of resistors, diodes, and transistor is provided between the terminal 281 and the feedback network. The various components therein have been given reference numbers identical with the numbers of the corresponding components in the arrangement just described, followed by the letter *a*. The transistors 288 and 288*a*, together with their associated resistors and diodes, form a shunt arm for the feedback network, the impedance of which is dependent upon whether neither of the transistors, ~~one~~ one of the transistors, or both of the transistors are conducting. When characters are being generated with both axes enlarged, both terminals 280 and 281 are held at a positive potential sufficient to render the transistors 288 and 288*a* conductive. Signals from the feedback network are thereby shunted through the parallel combination of the resistors 289 and 290, and the resistors 289*a* and 290*a*. If only one of the axes is to be enlarged, the one of the transistors 288 and 288*a* corresponding to the normal axis is cut off, increasing the resistance of the shunt path from the feedback network. The attenuation of the feedback signal is thereby reduced, reducing the gain of the feedback amplifier. Thus, the intensity signal or output signal of the transistor 249 is also decreased when a proportioning circuit reduces the writing speed.

The enlarge signals applied at the terminals 280 or 281 generally do not change during the display of a single character, but rather remain in one state during the entire period it takes to generate that character. It may be noted that when a character is enlarged along either the X-axis or Y-axis, the strokes having both X-axis and Y-axis components are at some angle other than 45°. The proper brightness for such strokes is achieved by appropriate adjustment of the variable resistors 289 and 289*a*.

The wave form 273 representing an example of the output of the transistor 249 shows a pedestal voltage or amplitude which is much greater than the increments added to the amplitude by the angled strokes. This is because the cathode-ray tube grid is typically biased well below cutoff in quiescence to allow for manufacturing tolerances and variations with age. The pedestal voltage raises the cathode-ray tube grid potential into the operating range for the desired brightness.

MODIFICATIONS AND ALTERNATIVE EMBODIMENTS

In operating the embodiment of FIG. 1 either as a stroke-type generator or as a dot-type generator, it may be desirable to incorporate a fourth wire in each set for producing a pulse indicative of the completion of the generation of each character. By utilizing this pulse to reset the sequential pulse generator 12 and to actuate the clamp circuit 35, a new character may be started almost immediately upon completing the previous character. This allows considerably higher average character generation rates by eliminating the need for going through a full sequence of core energizations for each character, since the end-of-character pulse may be produced

immediately following energization of the last core needed to generate the character. Thus, the total time required for each character is less for characters with fewer strokes or dots.

The sequential pulse generator 12, as detailed in FIG. 14, can be stopped and reset by merely interrupting momentarily the train of clock pulses applied to its input terminal 199. As shown in FIG. 23, the clock pulses may be supplied by a clock pulse generator 208, as is well known, via an AND gate 207. The enabling input of the AND gate 207 is coupled to one output of flip-flop 204. Upon receipt of a START pulse the flip-flop is set and enables the AND gate, permitting clock pulses to pass therethrough. Upon receipt of a STOP pulse from the fourth wire, the flip-flop is reset and the AND gate is disabled. The interruption of the clock pulse train for a sufficient time to delete one pulse from the train causes the sequential pulse generator to stop pulsing, and it returns quickly to its quiescent condition.

Even more time can be saved in the operation of the sequential pulse generator 12 if the clock pulse train is derived from a pulsed oscillator which is controlled by the flip-flop 204. Pulsed oscillators are well known, and are described, for example, on pp. 504-506 of the book *Pulse and Digital Circuits*, by Millman and Taub, published by McGraw-Hill in 1956. (Library of Congress Catalog Card No. 55-11930). In the pulsed oscillator alternate configuration, no AND gate is used and the clock pulses are fed directly from the clock generator to the input terminal 199 of the sequential pulse generator. The first clock pulse can be made to occur immediately after the start signal in the pulsed oscillator configuration, while the first pulse may occur randomly at any time up to one clock period after the start in the AND gate configuration.

As previously described, both enlarging circuits or diminishing circuits may be used as the proportioning circuits of FIG. 1. Satisfactory character generators can be made using only enlarging circuits, or only diminishing circuits, or both. Proportioning circuits may be used in either one of the two axes, or in both axes. If both an enlarging and a diminishing circuit is used in each axis, nine different combinations of X and Y proportioning factors are possible. The enlarging and diminishing circuits of FIG. 8 and FIG. 9 may be used either to establish the correct proportions of the generated characters, or to change the size of the characters. Obviously, if enlarging circuits are enabled in both axes simultaneously, the character may be made larger, without changing its shape, and the converse is possible using the diminishing circuits.

Referring now to FIG. 17, a character generator utilizing five wires per set, rather than three wires per set is illustrated diagrammatically. In those characters for which no blanking of the cathode-ray tube beam is required, only four wires per set are needed. In the embodiment of FIG. 17, each wire is wound to produce a positive pulse, one wire being threaded to generate the positive X-axis pulses and a separate wire being threaded to generate the negative X-axis pulses. A similar two-wire arrangement is utilized to produce the pulses which control the positive and negative Y-axis deflections. Any number of cores may be utilized, depending upon the number of available strokes desired. Sequential energization of the cores may be as previously described.

The positive X-axis deflection wires are all connected through an OR gate 291 to the charging means 292. Similar OR gates 293, 294 and 296 connect the negative X-axis, positive Y-axis and negative Y-axis deflection wires to the charging means 292. Particular diodes, not shown, of which the OR gates 291, 293, 294 and 296 are comprised, as in the previous embodiments, are rendered conductive by suitable selection circuitry, as previously described. The OR gate 291 is connected to a positive X-axis flip-flop 297 through an amplifier 298. Similarly, the OR gate 293 is connected to a negative X-axis flip-flop 299 through an amplifier 301. The OR gate 294 is connected to a positive Y-axis flip-flop 302 by an amplifier 303, and the OR gate 296 is connected to a negative Y-axis flip-flop 304 through an amplifier 306.

The outputs of the positive X-axis and negative X-axis flip-flops 297 and 299 are applied to an X-axis deflection current generator 307, the output of which is utilized to produce the X-axis deflection voltage. Similarly, the outputs of the positive Y-axis and negative Y-axis flip-flops 302 and 304 are applied to a Y-axis deflection current generator 308, the output of which is utilized to produce the Y-axis deflection voltage. The current generators 307 and 308 may be constructed as previously described.

Each of the flip-flops 297, 299, 302 and 304 is designed to be complemented only when pulses are applied thereto. Thus, a particular flip-flop is complemented when the slope (which may be plus, minus or zero) is to be changed for that particular axis at that particular time during the character writing period. This avoids unnecessary switching transients and discontinuities in the displayed characters. Accordingly, character segments consisting of two, three or four unit strokes in a straight line are drawn with no discontinuity in direction or intensity between strokes, since no pulses appear in the wires if no change of slope occurs. The fifth wire in each set which, as previously mentioned, is used to blank and unblank the cathode-ray tube beam, is connected through an OR gate 309 to an amplifier 311. The amplifier 311 drives the intensity control flip-flop 312 which, in turn, is connected to the intensity control 313. The intensity control 313 may be designed in accordance with previously described circuitry, and responds to the presence or absence of an output from the flip-flop 312 to control the grid potential. Variation in the output of the intensity control 313 may be provided, as in previous circuitry, for taking into account variations in the writing speed of the beam.

If desired, a sixth wire may be added to each set in the embodiment of FIG. 17 to stop the character generator when the required number of strokes for each character have been produced. As described in connection with the previous embodiments, this feature allows variable character writing times. Suitable means, not shown, may be provided in the embodiment of FIG. 17 for controlling the character size, as was incorporated in the previously described character generators. A clamp circuit, not shown, is required, and may be of the type previously described.

For some applications, a more complex character form, or a wider variety of available characters may be desirable. By increasing the number of wires in each set, a large number of available stroke directions may be made available. The embodiment of FIG. 18 illustrates a system capable of producing the 24 different strokes illustrated in FIG. 19, in an arrangement utilizing five wires per character plus an additional wire for intensity or blanking control where needed.

The five wires, *a* through *e*, in each set for character control are wound on the cores in the pattern of a 5-bit binary code, the wires being wound to produce pulses of one polarity only. Pulses in the five wires are fed through OR gates 315, 317, 318, 319 and 321, such OR gates being of multiple diode configuration as in the previously described embodiments. The outputs of each of the OR gates are amplified by pulse amplifiers 322, 323, 324, 326 and 327, respectively. After amplification, the pulses are fed to flip-flops 328, 329, 331, 332 and 333, respectively. The flip-flop outputs are fed to a code translator or code converter 334, which may be of any suitable circuit configuration for translating the 5-bit binary code applied thereto from the flip-flops to furnish up to eight outputs, depending upon the 5-bit binary code input.

Of the 32 possible combinations of the five bits in the flip-flops, 24 combinations are selected to correspond to 24 possible directions and stroke lengths, as indicated in FIG. 19. Four of the outputs of the code translator are fed to the X-axis sweep generator 336, and four of the outputs of the code translator are fed to the Y-axis sweep generator 337. The notations +1, +2, -1, etc. at the inputs to the sweep generators 336 and 337 refer to the resulting slopes of the ramp voltages across the storage capacitors for the X-axis and Y-axis deflection. For example, an input on +1 gives a positive deflection

slope of one unit, while an input on -2 gives an output signal with a negative slope of two units, and so on.

One form of the code translator is shown in FIG. 22. The five flip-flop 328, 329, 331, 332, and 333 each have two complementary outputs, identified as 0 and 1, respectively. The 10 outputs appear on the correspondingly labeled vertical binary code lines on FIG. 22. A total of 24 AND gates, each having five input terminals, have their inputs connected to selected ones of the 10 code lines, in an orderly fashion, according to the conventional binary weighting code. That is, the inputs of AND gate 1 are connected to the 1 output of the unit weighted flip-flop, and the 0 outputs of the 2, 4, 8, and 16 weighted flip-flops, the inputs of AND gate 2 are connected to the 0 output of 1, 4, 8, and 16 weighted flip-flop and to the 1 output of the 2 weighted flip-flop, etc. Only one AND gate can provide an output at any instant in time.

The outputs of the 24 AND gates are coupled to the inputs of the eight NOR gates. The AND gates may be connected to the NOR gates according to the convention that an output from AND gate 1 corresponds to stroke 1 in FIG. 19. Since stroke 1 is a stroke of unit length in X-direction and 0 length in the Y-direction, the output of AND gate 1 is coupled only to an input of the NOR gate labeled $+1X$. Likewise, the output of AND gate 3 is coupled to the NOR gate labeled $+2X$ and the NOR gate labeled $+1Y$, to produce a stroke which is the vector resultant of a two-unit X-component and a one-unit Y-component. The balance of the AND gates may be connected according to the same convention. All the AND gates, NOR gates and connections are not shown, to avoid unnecessary cluttering of the drawing. The code translator may be conveniently and compactly implemented with commercially available integrated circuit AND and NOR gates.

The function of the 24 AND gates is termed decoding. The function of the eight NOR gates is termed encoding. Together, the decoder and the encoder comprise the code translator or code converter 334.

The sixth wire in each set (wire f, FIG. 18), as previously mentioned, is utilized to blank and unblank the cathode-ray tube beam when required. Blank and unblank pulses are fed through an OR gate 338, amplified in an amplifier 339, and applied to an intensity control flip-flop 341. The intensity control flip-flop is connected to an intensity compensating circuit 342 which, as will be described subsequently, blanks and unblanks the beam of the cathode-ray tube in accordance with the operation of the flip-flop 341. The intensity compensating circuit 342 also varies the current of the cathode-ray tube beam to take into account the fact that several different beam velocities may be present in generating a character. As will be described, such variation in beam current is accomplished by sampling the sweep generator inputs and the signals produced by the character proportioning circuit, not shown, (such circuit being similar in operation and effect to the proportioning circuits illustrated in FIGS. 8 and 9).

If last-stroke wires are incorporated to enable the starting of a new character immediately upon completion of the previous character, such lines are fed through an OR gate 343 and an amplifier 344 to a suitable control flip-flop 204 (FIG. 23) to stop further energization of the cores and return the character generator to condition for starting the next character.

Referring now to FIG. 20, a circuit configuration which may be utilized for either of the X-axis or Y-axis sweep generators 336 or 337 in FIG. 18 is illustrated. Positive increments at the $+1$ rate are controlled by an NPN transistor 346 and a PNP transistor 347. The emitter of the transistor 346 is connected to ground through a resistor 348. The collector of the transistor 346 is connected to a source 349 of positive potential through a resistor 351. The collector of the transistor 346 is also connected to the emitter of the transistor 347 through a variable resistor 352 and a fixed resistor 353. The base of the transistor 347 is connected to a source 354 of fixed positive potential, less than the potential at 349, and the collector of the transistor 347 is connected to the storage capacitor 356 for the X-axis or Y-axis deflection voltage. An NPN transistor

357 is triggered into conduction by suitable signals applied to its base terminal 358 at the end of the generation of a character in order to discharge the storage capacitor 356.

The associated NOR gate 2 of the code translator 354 maintains the base of the transistor 346 at a positive potential, causing the transistor to conduct. The value of the resistors 351 and 348 are selected such that the emitter potential of the transistor 347 is lower than the potential on its base. Accordingly, the transistor 347 is nonconductive. Upon the translation of a code indicating a change in deflection voltage at the $+1$ rate, the terminal 359 is dropped to near ground by NOR gate 2, causing the transistor 346 to be cut off. This raises the emitter potential of the transistor 347 higher than the base potential because of the source 349 is substantially higher in voltage than the source 354. The values of the resistors 351, 352, 353, and the adjustment of the variable resistor 352, are selected such that the transistor 347 operates as a constant current generator, its base voltage being fixed and its collector current being nearly constant, at the $+1$ rate.

The $+2$ rate of incremental change in voltage deflection is controlled by an NPN transistor 361 and a PNP transistor 362. The emitter of the transistor 361 is grounded through a resistor 363, and the collector is connected to the source 349 through a resistor 364. The collector of the transistor 361 is also connected through a variable resistor 366 and a fixed resistor 367 to the emitter of the transistor 362. The base of the transistor 362 is connected to the positive voltage source 354, and the collector of the transistor 362 is connected to the storage capacitor 356.

Operation of the transistors 361 and 362 is similar to the operation of the transistors 346 and 347. The transistor 362 conducts when the transistor 361 is cut off by a low potential applied to its base terminal 368 by NOR GATE 1 of the code translator. The value of the resistors 364, 366 and 367, and the adjustment of the variable resistor 366, are selected such that the transistor 362 operates as a constant current generator with fixed base voltage and constant collector current, and such that its charging rate of the storage capacitor 356 is at the $+2$ rate.

Negative incremental changes in the voltage on the storage capacitor 356 are produced in a manner similar to positive incremental changes by means of suitable negative constant current generators. These are also illustrated in FIG. 20, the -1 rate generator comprising a PNP transistor 369 and an NPN transistor 371. The base of the transistor 369 is grounded and the emitter of the transistor is connected through a resistor 372 to an input terminal 373. The collector of the transistor 369 is connected through a resistor 374 to a source 376 of negative potential. The collector is also connected through a variable resistor 377 and a fixed resistor 378 to the emitter of the transistor 371. The collector of the transistor 371 is connected to the storage capacitor 356, and the base is connected to a source 379 of negative potential. The voltage of the source 379 is substantially less negative than the voltage of the source 376.

With the transistor 369 conductive, the emitter potential of the transistor 371 is near ground, and the transistor is cut off. Where a negative change in the storage capacitor deflection voltage at the -1 rate is required, the potential at the terminal 373 is dropped to near ground from its normal positive voltage by NOR gate 3 code translator such that the transistor 369 is cut off. This drops the potential on the emitter of the transistor 371 to below that of the base, due to the fact that the negative voltage of the source 376 is more negative than the negative voltage of the source 379. Accordingly, the transistor 371 acts as a constant negative current generator, its base voltage being fixed and its collector current being nearly constant. The values of the resistors 374, 377 and 378, and the setting of the variable resistor 377, are selected such that the rate of change in voltage on the storage capacitor 356 is at the -1 rate.

Linear changes in deflection voltage on the storage capacitor 356 are produced in a similar manner by a PNP transistor 381 and an NPN transistor 382. The base of the transistor 381

is grounded, its emitter connected to an input terminal 383 by a resistor 384, and its collector connected to the source 376 through a resistor 386. The collector of the transistor 381 is also connected through a variable resistor 387 and a fixed resistor 388 to the emitter of the transistor 382. The base of the transistor 382 is connected to the source 379 and the collector is connected to the storage capacitor 356.

With no change at the -2 rate, the terminal 383 is maintained at a positive potential by the code translator. The transistor 381 therefore conducts, and the transistor 382 is cut off, since its emitter potential is more positive than its base. Upon the requirement of a linear change at the -2 rate, the potential at 383 is dropped to near ground by NOR gate 4 of the code translator, cutting off the transistor 381. The emitter potential of the transistor 382 therefore drops, and the transistor, having a fixed base voltage, provides a constant collector current. The values of the resistors 388, 387 and 386, and the setting of the variable resistor 387, are selected so that the change in voltage on the capacitor 356 due to the conduction of the transistor 382 is at the -2 rate.

The intensity compensating circuit 342 shown in FIG. 18 may be of any suitable type which automatically computes intensity signals to compensate for the five different writing speeds existing in the generation of characters with the strokes illustrated in FIG. 19. A satisfactory circuit for accomplishing this is illustrated in FIG. 21. The $+1$, $+2$, -1 and -2 inputs to the Y sweep generator 337 of FIG. 18 are tapped off and applied to the bases of the transistors 388, 389, 391 and 392, respectively. The collectors of the mentioned transistors are coupled directly to ground, and the emitters are connected through resistors 393, 394, 396 and 397, respectively, to the base of a PNP transistor 398. The resistors 393 and 396 are equal in resistance and approximately four times the resistance of the resistors 394 and 397, which are also equal in resistance. A resistor 399 connects the base of the transistor 398 to a source 401 of positive potential. The resistor 399 is approximately two times the resistance of resistor 394 and 397. The collector of the transistor 398 is tied directly to ground, and the emitter is connected through a resistor 402 to a point 403.

Four transistors 404, 406, 407 and 408 are provided for sampling signals applied to the X-axis sweep generator, and have their bases tied to the $+1$, $+2$, -1 and -2 sweep generator inputs, respectively. The collectors of the mentioned transistors are directly connected to ground, and the emitters are connected through resistors 409, 411, 412 and 413, respectively, to the base of a PNP transistor 414. The base of the transistor 414 is connected through a resistor 416 to a source 417 of positive potential. The collector of the transistor 414 is tied directly to ground, and the emitter is connected through a resistor 418 to the point 403. The resistors 409 and 412 are equal, and are four times the value of the resistors 411 and 413, which are also equal. The resistor 416 is two times the resistance of resistor 411 or 413. The value of the resistors 411 and 413 is equal to that of the resistors 394 and 397, and the value of the resistors 409 and 412 is equal to that of the resistors 393 and 396.

The resistors 393, 394, 396 and 397, with resistor 399 form a binary weighted combining network. The transistors 388, 389, 391 and 392 switch the binary signals applied to the resistor network. Transistor 398 is an emitter follower which serves as a buffer amplifier, and prevents the succeeding stages from loading the network. For purposes of explanation, the resistance of resistors 394, 397 may be designated R , so that the resistors 393, 396 have a resistance $4R$, and resistor 399 has a resistance of $2R$. In operation, only one of the four inputs to the transistors 388, 389, 391, 392 may be at the zero signal level at any time, the other three being at a positive potential. A transistor in this group conducts only when its base is near ground, as will be explained. If transistor 388 or 391 is on, the base of transistor 398 is fixed at a voltage equal to two-thirds of the voltage at terminal 401, because of a resistance of $2R$ (399) to terminal 401 and a resistance of $4R$

(393 or 396) to ground. The signal developed across resistor 399 is thus one-third of the voltage at terminal 401. Alternatively, if transistor 389 or 392 is on, the voltage at the base of transistor 398 is one-third of the voltage at terminal 401 because of a resistance of R (394 or 397) to ground and a resistance of $2R$ to terminal 401. The signal developed across resistor 399 is then two-thirds of the voltage at terminal 401. If any one of the four transistors is on, the voltage at the base of transistor 398 is below the signal voltage on the bases of the other three transistors. The other three transistors are thus shut off, since their emitter voltages are below their base voltages. Thus a binary weighted signal is produced at the base of transistor 398, with reference to terminal 401.

Transistors 404, 406, 407, and 408, with resistors 409, 411, 412, 413 and 416, produce a binary weighted signals in response to binary inputs from the code converter of the X-axis in the same manner. The binary weighted signal for the X-axis is coupled to the base of transistor 414.

Transistors 398 and 414 are emitter followers, which couple the binary weighted signals from the Y and X combining networks to the resistors 402 and 418, respectively. The resistors 402 and 418 are part of a nonlinear combining network, as will be explained.

The point 403 is connected through a potentiometer 419 to a source 423 of positive potential. The resistors 402 and 418, together with potentiometer 419 and source 423, comprise a combining network with nonlinearly adds the output signals of transistors 398 and 414, representing the Y- and X-axis deflection rates, respectively. The signal developed across the potentiometer 419 when both axes are deflecting at a given rate is 1.4 times the signal developed when only one axis is deflecting at the same rate, as explained before in connection with FIG. 16. A portion of the signal across potentiometer 419 is coupled through a resistor 421 to the base of a PNP transistor 422. The base of the transistor 422 is also connected through a resistor 424 to the tap of a potentiometer 426. The potentiometer 426 is connected between a source 427 of positive potential and a further source 428 of negative potential.

The collector of the transistor 422 is connected through a resistor 429 to a source 431 of negative potential. The emitter of the transistor 422 is connected directly to a source 432 of positive potential. In the preferred embodiment, the source 432, the source 401, and the source 417 are all of the same voltage. The collector of the transistor 422 is also connected through a resistor 433 to the base of an NPN transistor 434. The collector of the transistor 434 is connected directly to a source 436 of positive potential, and the emitter of the transistor 434 is connected to ground through a grid bias load resistor 437. The emitter is also connected to the grid of the cathode-ray tube, providing the bias voltage thereto developed across the resistor 437. A feedback resistor 438 connects the emitter of the transistor 434 with the base of the transistor 422, and thus the transistors 422 and 434 constitute a linear feedback amplifier.

The base of the transistor 434 is connected to the collector of an NPN transistor 439, the emitter of which is directly coupled to ground. Signals from the intensity flip-flop 341 (FIG. 18) are applied through a resistor 441 to the base of the transistor 439. In the presence of a positive signal applied to the base of the transistor 439, such transistor becomes conductive, cutting off the transistor 434 and blanking the cathode-ray tube beam. When the intensity flip-flop 341 changes its state so that no output is provided, the beam is unblanked, since the transistor 439 becomes nonconductive and transistor 434 becomes conductive. The output signal at the emitter of the transistor 434 is at the appropriate level for the speed of the beam for the particular stroke being produced, in accordance with the operation of the binary weighted networks in each axis, and the nonlinear network described previously, which provide a signal of proper amplitude to the feedback amplifier. The various levels of output voltage may be adjusted by appropriate adjustment of the potentiometers 419 and 426. The particular level of the output of the transistor

434, of course, changes during the generation of a character. However, the level of such output remains constant for at least the duration of a single stroke. In the embodiment of FIG. 18, proportioning circuits (not shown) may be used similar to those described in connection with the embodiment of FIG. 1. If proportioning circuits are used, the intensity compensating circuit of FIG. 21 may be modified to respond to enlarge and diminish signals as taught by FIG. 16 and the description thereof.

In the embodiment of FIG. 18, a system has been described with the flip-flops 328, 329, 331, 332 and 333 preceding the code translator 334. In another version, the flip-flops may be positioned between the code translator and the sweep generators 336 and 337. The flip-flops following the code translator are operated by appropriate pulses produced by the code translator, rather than directly from the pulses produced by the wires wound on the magnetic cores.

While the character generators described herein are shown and described as connected to the deflection plates of an electrostatically deflected cathode ray tube, they may also be used to drive the deflection coils of a magnetically deflected cathode-ray tube, via a pair of suitable deflection amplifiers. Any amplifier having a high input impedance, a sufficient current capability in the output stage, and fast response may be used.

FIGS. 24 and 25 show circuitry which may be used to drive one axis of a deflection yoke if a magnetically deflected cathode-ray tube is used. It is to be understood that the amplifier for the other axis is identical. The input signal from one of the storage capacitors 16, 17 of the character generator is coupled to the buffer amplifier shown in FIG. 24. The buffer amplifier has unity gain, with respect to the signal voltages, but has a very high input impedance and low output impedance. The high input impedance is necessary to prevent undesired discharge of the storage capacitor, 16 or 17, during the generation of a character. The input stage transistor 501 is coupled as an inverting amplifier with voltage gain. The second stage transistor 502 is another inverting amplifier with voltage gain. The second and third stages include transistors 503 and 504 both coupled as emitter followers. The output signal from the emitter of the transistor 504 is fed back unattenuated to the emitter of the transistor 501, the input stage, via a resistor 505. Thus, because of unity feedback, the closed-loop gain of the buffer amplifier is unity. Since the emitter voltage of the transistor 501 follows the base voltage almost exactly, the base-emitter current flow is very small; i.e. the input current to the base from the capacitor 16, 17 is very small so the capacitor is not discharged. Resistors 507 and 508 are a voltage divider which provides a suitable operating potential or bias to the emitter of the transistor 502. A capacitor 509 is connected to the emitter of the transistor and acts as a decoupling capacitor.

The low impedance output signal from FIG. 24 is coupled to the yoke driving amplifier of FIG. 25 at terminal *b*. The yoke driver converts a voltage signal at its input to a proportional current signal in its output stage, which current is passed through a winding 510 of the deflection yoke. The yoke driver is a two-stage DC coupled feedback amplifier. The input signal is applied through the input resistor 511 to the base of a transistor 512. The transistor 512 is coupled as an emitter follower, its output being coupled to the base of a power transistor 513. Output current from the collector of the power transistor flows through the yoke winding 511 and then through a sensing resistor 514 to a positive power supply. A feedback voltage is developed across the resistor 514 which is proportional to yoke current. The feedback voltage is applied to the base of the input transistor 512 via a feedback resistor 516. Thus, by feedback action, the current in the yoke is required to be linearly proportional to the input voltage at terminal *b*. A transistor 517, which is a constant current generation, provides sufficient bias current to the base of the input transistor 512 to operate it in an amplifying range; i.e. neither in cutoff nor in saturation.

In may therefore be seen that the invention provides an improved character generator which makes use of stored information codes in the form of a pattern of wires and magnetic cores consisting of as few as two wires per character. This makes possible a considerable reduction in components, and since only one set of wires, corresponding to a specific character to be generated, is active at any one time, selection may be accomplished by forming closed loop configurations of only those wires which are part of the desired character in order to detect the pulses. In this manner a single current pulse detector or readout amplifier is required per axis to generate the information codes for all the characters. Additional characters may be readily added by installing the appropriate number of wires per character, each wire terminating in a diode. Interference from unselected characters is minimized, since practically no current will be induced in those wires which are not part of a selected character. High writing speeds are readily attainable, and by adding an additional wire per set, generation of characters may be terminated as soon as the character is written, substantially reducing the average time for generation of the characters. Where the apparatus is utilized as a dot-type character generator, it is possible to obtain a relatively high ratio of the beam on to beam off duty cycle, resulting in the production of bright characters, since the beam is not required to dwell upon a large number of blanked dot positions. Moreover, in the dot-type character generator configuration, the possible arrangements of the available dots is virtually unrestricted and is extremely flexible. Character size may be readily varied in either the dot-type or stroke-type generators. Since a capacitor is connected between each deflection output terminal and ground, the generators are relatively insensitive to and free of spurious noise signals which might otherwise distort the displayed characters. Capacitive loading of the deflection output terminals by wiring capacitance or by the capacitance of the deflection plates of the cathode-ray tube does not reduce the speed of the generator, as its effect may be eliminated by a corresponding reduction in the storage capacitors of the generator. Furthermore, in the stroke-type generator, smooth, continuous characters of uniform brightness are readily achieved.

Various modifications of the invention in addition to those shown and described herein will become apparent to those skilled in the art from the foregoing description and accompanying drawings. Such modifications are intended to fall within the scope of the appended claims.

1. For use with a cathode-ray tube having X- and Y-axis deflection means for producing beam deflections parallel to X and Y axes to describe a character, a character generator comprising, a plurality of magnetic cores, means for sequentially energizing said cores one at a time, at least one set of wires for producing information to generate a predetermined character, at least one wire of which is wound on selected ones of said cores to produce, upon energization of said cores, a sequence of pulses representative of incremental changes in beam deflection, charging means, means connecting said wires to said charging means, said charging means being responsive to the pulses produced in said wires to produce constant current output signals each corresponding to an increment of X- or Y-axis deflection, and first and second storage means connected to said charging means for receiving the X-axis constant current output signals and the Y-axis constant current output signals, respectively, said first and second storage means thereby each producing a deflection voltage corresponding to the sum of the charging means output signals representing increments of deflection in the respective axis, said first and second storage means being adapted for connection to the X- and Y-axis deflection means, respectively, to apply deflection voltage thereto.

2. A character generator according to claim 1 including an intensity circuit adapted for connection to the electron gun of the cathode-ray tube for blanking and unblanking the cathode-ray tube beam in response to intensity control pulses

applied to said intensity circuit, wherein said at least one set of wires includes at least one wire wound on selected ones of said cores to produce intensity control pulses for the predetermined character upon energization of said cores, wherein said charging means are adapted to produce output signals which are substantially shorter in duration than the time between energizations of successive magnetic cores, and wherein said intensity circuit is adapted to produce unblank signals during the period said charging means are off, said character generator thereby producing characters defined by a series of dots.

3. A character generator according to claim 1 wherein said charging means are adapted to produce output signals which are substantially equal in duration to an integral multiple of the time period between energizations of successive cores, for defining characters by means of line segments.

4. A character generator according to claim 1 wherein each of said storage means comprises a capacitor.

5. A character generator according to claim 1 including a plurality of sets of wires, one set for each character to be generated, wherein the means connecting the wires to the charging means comprise selecting switch means between each set of wires and said charging means, and wherein means are provided for selectively closing said selecting switch means to select characters for generation.

6. A character generator according to claim 1 wherein at least one of said storage means comprises a capacitor, wherein diminishing means are provided including a further capacitor and diminishing switch means selectively coupling said further capacitor in parallel with said capacitor in said one storage means, and wherein means are provided to selectively close said diminishing switch for a time interval sufficient to generate one character, thereby to diminish the character in at least one axis.

7. A character generator according to claim 1 wherein at least one of said storage means comprises a pair of capacitors, and wherein enlarging switch means are provided to selectively disable one of said pair of capacitors in said one storage means, and wherein means are provided to selectively open said enlarging switch means for a time interval sufficient to generate one character, thereby to enlarge the character in at least one axis.

8. A character generator according to claim 1 wherein one wire in at least one set is wound on a magnetic core following the last magnetic core used for generation of the character associated with that set, and wherein means are provided responsive to production of pulses in said one wire for stopping further sequential energization of said cores.

9. A character generator according to claim 1 wherein said wires in each of said sets are wound on the cores to produce a binary code representative of incremental changes in beam deflection in both X and Y axes upon energization of each core, and wherein said charging means include a binary code converter for decoding said binary codes and initiating production of constant current output signals corresponding thereto.

10. A character generator according to claim 1 wherein each set contains at least two wires, one wire defining X-axis deflections and the other wire defining Y-axis deflections.

11. A character generator according to claim 1 wherein each set contains at least four wires, two wires defining first and second orders of magnitude of X-axis deflection, respectively, and the other two wires defining first and second orders of magnitude of Y-axis deflection, respectively.

12. A character generator according to claim 1 wherein a first wire in each set is wound upon selected ones of said cores to produce upon energization of said cores, a first sequence of pulses of uniform amplitude, each pulse representing an incremental change in beam deflection on one axis; a second wire in each set is wound upon selected ones of said cores to produce, upon energization of said cores, a second sequence of pulses of uniform amplitude, each pulse representing an incremental change in beam deflection in the other axis; and said charging means comprise a first charging means respon-

sive to pulses produced in said first wire of each set and providing output signals to said first storage means, and a second charging means responsive to pulses produced in said second wire of each set and providing output signals to said first storage means.

13. A character generator according to claim 12 wherein said first wire in at least one set is wound to produce a first sequence comprising both positive polarity and negative polarity pulses; said second wire in at least one set is wound to produce a second sequence comprising both positive polarity and negative polarity pulses; and each of said charging means is adapted to produce constant current output signals of one polarity in response to positive pulses and constant current output signals of the other polarity in response to negative pulses; whereby positive increments of deflection are produced by pulses of one polarity and negative increments of deflection are produced by pulses of the other polarity.

14. A character generator according to claim 12 including an intensity circuit coupled to the electron gun of the cathode-ray tube for providing intensity control signals to the gun in response to intensity control pulses; wherein a third wire in at least one set of wires is wound upon selected ones of said cores to produce, upon energization of said cores, a third sequence of pulses, said third sequence of pulses being representative of the intensity variations required to generate the character; and the pulses in said third sequence are coupled from said third wire via said connecting means to said intensity circuit; whereby the pulses in said third sequence control the intensity of the cathode-ray tube.

15. A character generator according to claim 12 wherein said charging means are adapted to produce output signals which are substantially shorter in duration than the time between energizations of successive magnetic cores, and wherein said intensity circuit is adapted to produce intensifying signals during the period said charging means are off, said character generator thereby producing characters defined by a series of dots.

16. A character generator according to claim 12 adapted to generate signals describing a selected one of a plurality of characters, comprising: a plurality of selection terminals, one terminal being provided for each of the plurality of characters; means to selectively apply a selection signal to one of the selection terminals for a time interval sufficient to generate one character, said one selection terminal being maintained by said selection means substantially above a predetermined threshold potential and the balance of said selection terminals being maintained by said selection means substantially below said threshold potential; a first deflection control terminal coupled to the input of said first charging means; and a second deflection control terminal coupled to the input of said second charging means; means biasing each deflection control terminal toward a reference potential, said reference potential being below said threshold potential; wherein one set of wires is provided for each of the plurality of characters; wherein said means connecting said wires to said charging means comprise said first and second deflection control terminals, said biasing means, and a plurality of diodes, one diode being provided for each wire; wherein a first end of every wire in each set is coupled to one of said selection terminals, said terminal being common to all the wires of the set; wherein the second end of each wire is coupled to the anode of one of said diodes; wherein the cathode of every diode coupled to the first wire of any set is coupled to said first deflection control terminal; and wherein the cathode of every diode coupled to the second wire of any set is coupled to said second deflection control terminal; whereby, every diode coupled to a wire of the set which is coupled to the selection terminal above the threshold potential is conductive and passes every pulse produced in the wire coupled thereto when said cores are sequentially energized; and every diode coupled to a wire of a set which is coupled to a selection terminal below the threshold potential is nonconductive and passes none of the pulses produced in the wire coupled thereto when the cores sequentially energized.

17. A character generator according to claim 12 adapted to generate signals describing a selected one of a plurality of characters, comprising: a plurality of selection terminals, one terminal being provided for each of the plurality of characters; means to selectively apply a selection signal to one of the selection terminals for a time interval sufficient to generate one character, said one selection terminal being maintained by said selection means substantially below a predetermined threshold potential and the balance of said selection terminals being maintained by said selection means substantially above said threshold potential; a first deflection control terminal coupled to the input of said first charging means; and a second deflection control terminal coupled to the input of said second charging means; means biasing each deflection control terminal toward a reference potential, said reference potential being above said threshold potential; wherein one set of wires is provided for each of the plurality of characters; wherein said means connecting said wires to said charging means comprise said first and second deflection control terminals, said biasing means, and a plurality of diodes, one diode being provided for each wire; wherein a first end of every wire in each set is coupled to one of said selection terminals, said terminal being common to all wires of the set; wherein the second end of each wire is coupled to the cathode of one of said diodes; wherein the anode of every diode coupled to the first wire of any set is coupled to the first deflection control terminal; and wherein the anode of every diode coupled to the second wire of any set is coupled to said second deflection control terminal; whereby, every diode coupled to a wire of the set which is coupled to the selection terminal below the threshold potential is conductive and passes every pulse produced in the wire coupled thereto when said cores are sequentially energized; and every diode coupled to a wire of a set which is coupled to a selection terminal above the threshold potential is nonconductive and passes none of the pulses produced in the wire coupled thereto when the cores are sequentially energized.

18. A character generator for providing signals describing a selected character to drive the X-axis deflecting devices and the Y-axis deflecting devices of a two axis graphical display, comprising: a plurality of magnetic cores; means for sequentially energizing said cores; a plurality of sets of control wires wound on said cores, at least one of said sets comprising at least one X-axis control wire wound on selected ones of said cores to produce a first sequence of pulses at uniform amplitude upon energization of said cores, and at least one Y-axis control wire wound on selected ones of said cores to produce a second sequence of pulses of uniform amplitude upon energization of said cores the winding of said X-axis control wire and said Y-axis control wire upon said cores being a function of the shape of the selected character, said first sequence of pulses being representative of the sequence of X-axis deflections required to generate the selected character, and said second sequence of pulses being representative of the sequence of Y-axis deflections required to generate the selected character; first and second charging means each providing constant current output signals in response to receipt of pulses; gating means for passing pulses from the X-axis and Y-axis control wires of a selected one of said sets of control wires corresponding to the selected character to said first and second charging means, respectively; and first and second storage means, said first storage means being connected to receive and accumulate the constant current signals from said first charging means, and said second storage means being connected to receive and accumulate the constant current signals from said second charging means, said first storage means providing an output voltage signal representative of the X-axis deflections required to generate the selected character, and said second storage means providing an output voltage signal representative of the Y-axis deflections required to generate the selected character.

19. A character generator according to claim 18 comprising: an intensity circuit adapted to provide intensity control signals to the intensity control device of the graphical display

in response to intensity control pulses; wherein at least one set of control wires includes at least one intensity control wire wound on selected ones of said cores to produce a third sequence of pulses upon energization of said cores, said third sequence of pulses being representative of the sequence of intensity variations required to describe the character; and wherein said gating means are operable to receive pulses from said intensity control wire and to provide pulses to said intensity circuit; whereby the pulses in said intensity control wire control the intensification of the graphical display.

20. A character generator according to claim 19 wherein: said charging means are adapted to provide constant current output signals each having a duration substantially equal to an integral number of said periods between successive core energization, and said intensity circuit is adapted to provide intensifying signals each having a duration substantially equal to an integral number of periods between successive core energizations, whereby the character is described on the graphical display as a plurality of sequentially connected straight line strokes.

21. A character generator according to claim 20 wherein: said charging means are adapted to provide constant current output signals, each beginning upon the receipt of a pulse from an associated control wire and ending upon the receipt of the next pulse from the same wire; and at least one wire of at least one set of control wires is wound to produce at least one pair of adjacent pulses spaced apart in time by an interval substantially equal to a plurality of the periods between successive core energizations; whereby the charging means receiving said pair of pulses produces an extended constant current signal with a duration of a plurality of the periods between successive energizations; and whereby the storage means receiving said extended constant current signal provides a deflection voltage without discontinuities during said interval.

22. A character generator according to claim 21 wherein: an X-axis control wire of at least one set of control wires is wound to provide at least one pair of adjacent X-axis pulses spaced apart by an X-axis interval substantially equal to a plurality of the periods between successive core energizations; a Y-axis control wire of the same set is wound to produce at least one pair of adjacent Y-axis pulses spaced apart by a Y-axis interval substantially equal to a plurality of the periods between successive core energizations; said X-axis interval and said Y-axis interval coincide in time for a plurality of the periods between successive core energizations; whereby a straight line segment is generated on the graphical display without discontinuities during the interval of coincidence.

23. A character generator according to claim 19 wherein: each pulse produced in an axis control wire represents a predetermined increment of deflection on the graphical display; each charging means provides a discrete constant current output signal in response to each pulse received from the associated control wire; each discrete constant current output signal has a duration substantially less than the period between successive energizations of the cores; each intensity control signal has a duration not more than the difference between the core energization period and the duration of the constant current signal; whereby the character is described as a pattern of sequential dots on the graphical display device.

24. A character generator according to claim 18 wherein: at least one of said storage means comprises a storage capacitor; proportioning means are provided comprising a further capacitor, proportioning switch means connected to selectively couple said further capacitor in parallel with said storage capacitor, and means is selectively actuate said proportioning switch means according to a dimension of the character to be described; whereby the dimension of the character generated on the graphical display in at least one axis is the smaller of two predetermined dimensions when said storage capacitor and said further capacitor are coupled in parallel, and the larger of the two predetermined dimensions when said capacitors are not coupled in parallel.

25. A character generator according to claim 18 wherein: one X-axis control wire in each set is wound to produce said first sequence of pulses; said first sequence of pulses comprises both positive polarity and negative polarity pulses; one Y-axis control wire in each set is wound to produce said second sequence of pulses; said second sequence of pulses comprises both positive polarity and negative polarity pulses; one Y-axis control wire in each set is wound to produce said second sequence of pulses; said second sequence of pulses comprises both positive polarity and negative polarity pulses; and said first and second charging means are each adapted to produce constant current output signals of one polarity in response to positive pulses and constant current output signals of the other polarity in response to negative pulses; whereby the sequence of X-axis deflections and Y-axis deflections required to generate the character are determined by said one X-axis control wire and said one Y-axis control wire.

26. A character generator according to claim 18 adapted to generate signals describing a selected one of a plurality of characters, comprising: a plurality of selection terminals, one terminal being provided for each of the plurality of characters; means to selectively apply a selection signal to one of the selection terminals for a time interval sufficient to generate one character, said one selection terminal being maintained by said selection means substantially above a predetermined threshold potential and the balance of said selection terminals being maintained by said selection means substantially below said threshold potential; a first deflection control terminal coupled to the input of said first charging means; a second deflection control terminal coupled to the input of said second charging means; means biasing each deflection control terminal toward a reference potential, said reference potential being below said threshold potential; wherein one set of wires is provided for each of a plurality of characters; wherein said gating means comprise said first and second deflection control terminals, said biasing means, and a plurality of diodes, one diode being provided for each wire; wherein a first end of every wire in each set is coupled to one of said selection terminals, said one terminal being common to all the wires of the set; wherein the second end of each wire is coupled to the anode of one of said diodes; wherein the cathode of every diode coupled to the X-axis control wire of any set is coupled to said first deflection control terminal and wherein the cathode of every diode coupled to the Y-axis control wire of any set is coupled to said second deflection control terminal; whereby, every diode coupled to a wire of the set which is coupled to the selection terminal above the threshold potential is conductive and passes every pulse produced in the wire coupled thereto when said cores are sequentially energized; and every diode coupled to a wire of a set which is coupled to a selection terminal below the threshold potential is nonconductive and passes none of the pulses produced in the wire coupled thereto when the cores are sequentially energized.

27. A character generator according to claim 18 adapted to generate signals describing a selected one of a plurality of characters, comprising: a plurality of selection terminals, one terminal being provided for each of the plurality of characters; means to selectively apply a selection signal to one of the selection terminals for a time interval sufficient to generate one character, said one selection terminal being maintained by said selection means substantially below a predetermined threshold potential and the balance of said selection terminals being maintained by said selection means substantially above said threshold potential; a first deflection control terminal coupled to the input of said second charging means; a second deflection control terminal coupled to the input of said second charging means; means biasing each deflection control terminal toward a reference potential, said reference potential being above said threshold potential; wherein one set of wires is provided for each of the plurality of characters; wherein said gating means comprise said first and second deflection control terminals, said biasing means, and a plurality of diodes, one diode being provided for each wire; wherein a first end of

every wire in each set is coupled to one of said selection terminals, said one terminal being common to all wires of the set; wherein the second end of each wire is coupled to the cathode of one of said diodes; wherein the anode of every diode coupled to the X-axis control wire of any set is coupled to said first deflection control terminal; and wherein the anode of every diode coupled to the Y-axis control wire of any set is coupled to said second deflection control terminal; whereby, every diode coupled to a wire of the set which is coupled to the selection terminal below the threshold potential is conductive and passes every pulse produced in the wire coupled thereto when said cores are sequentially energized; and every diode coupled to a wire of a set which is coupled to a selection terminal above the threshold potential is nonconductive and passes none of the pulses produced in the wire coupled thereto when the cores are sequentially energized.

28. A character generator for providing signals describing a character to drive the X-axis deflecting devices and the Y-axis deflecting devices of a two-axis graphical display, comprising: a number N of magnetic cores; means for sequentially energizing said cores; at least one set of control wires wound on said cores, said set comprising M deflection control wires, each of the M wires being wound on selected ones of said cores to produce a coded sequence of pulses of uniform amplitude upon energization of said cores the winding of said deflection control wires upon said cores being a function of the shape of the character, whereby the M deflection control wires produce a sequence of N binary coded words each of M binary bits; gating means comprising deflection gating means connected to receive binary coded words from said deflection control wires; code converter means connected to receive binary coded words from said deflection gating means, and adapted to produce in response to said words at least one sequence of deflection control signals representative of the sequence of X-axis deflections required to generate the character and at least one sequence of deflection control signals representative of the Y-axis deflections required to generate the character; first and second charging means, said first charging means being connected to receive the sequence of X-axis deflection control signals from said code converter, and said second charging means being connected to receive the sequence of Y-axis deflection control signals from said code converter said first and second charging means each providing constant current output signals in response to said deflection control signals; first and second storage means, said first storage means being connected to receive and accumulate the constant current signals from said first charging means, and said second storage means being connected to receive and accumulate the constant current signals from said second charging means, said first storage means providing an output voltage signal representative of the X-axis deflections required to generate the character, and said second storage means providing an output voltage signal representative of the Y-axis deflections required to generate the character.

29. A character generator according to claim 28 comprising: an intensity circuit adapted to provide intensity control signals to the intensity control device of the graphical display in response to intensity control pulses; wherein; least one set of control wires further comprises at least one intensity control wire wound on selected ones of said cores to produce another sequence of pulse upon energization of said cores, said other sequence of pulses being representative of the sequence of intensity variations pulses to generate the character; and said gating means include intensity gating means connected to receive pulses from said intensity control wire and to provide pulses to said intensity circuit; whereby the pulses in said intensity control wire control the intensification of the graphical display.

30. A character generator according to claim 29 wherein: said code converter means are adapted to produce deflection control signals each having a duration substantially equal to an integral number of the periods between successive core energizations; said charging means are adapted to provide constant

current output signals each having a duration equal to the duration of the deflection control signal coupled thereto; and said intensity circuit is adapted to provide intensifying signals each having a duration substantially equal to an integral number of the periods between successive core energizations; whereby the character is described on the graphical display as a plurality of sequentially connected straight line strokes.

31. A character generator according to claim 30 wherein: the code converter means are adapted to provide deflection control signals, each beginning upon the receipt of a binary coded word from the deflection control wires of a set and ending upon the receipt of a later binary coded word from the deflection control wires of the same set; the deflection control wires of at least one set of wires are wound to produce at least one extended deflection control signal extending over an interval substantially equal to a plurality of the periods between successive core energizations; whereby the charging means receiving said extended deflection control signal produces an extended constant current output signal with a duration of a plurality of the periods between successive energizations; and the storage means receiving said extended constant current signal provides a deflection voltage without discontinuity during said interval.

32. A character generator according to claim 31 wherein: the deflection control wires of at least one set of wires are wound to produce at least one extended X-axis deflection control signal extending over an interval substantially equal to a plurality of the periods between successive core energizations, at least one extended Y-axis deflection control signal extending over an interval substantially equal to a plurality of the periods between successive core energizations, said extended X-axis deflection control signal being coincident in time for a plurality of the periods between successive core energizations; whereby a straight line segment is generated on the graphical display without discontinuities during the interval of coincidence.

33. A character generator according to claim 29 wherein: the code converter means are adapted to produce sequences of deflection control pulses; said charging means are adapted to provide constant current output signals each having a duration substantially equal to an integral number of the periods between successive core energizations; and said intensity circuit is adapted to provide intensifying signals each having a duration substantially equal to an integral number of the

45

periods between successive core energizations; whereby the character is described on the graphical display as a plurality of sequentially connected straight line strokes.

34. A character generator according to claim 33 wherein: 5 the charging means are adapted to provide constant current output signals each beginning upon the receipt of a pulse from a sequence of deflection control pulses and ending upon the receipt of the next pulse from the same sequence; the deflection control wires of at least one set of wires are wound to produce at least one pair of deflection control pulses spaced apart in time by an interval substantially equal to a plurality of the periods between successive core energizations; whereby the charging means receiving said pair of pulses produces an extended constant current signal with a duration of a plurality 10 of the periods between successive core energizations; and the storage means receiving said extended constant current signal provides a deflection voltage without discontinuities during said interval.

35. A character generator according to claim 34 wherein: 20 the deflection control wires of at least one set of wires are wound to produce at least one pair of X-axis deflection control pulses spaced apart in time by an X-axis interval equal to a plurality of the periods between successive core energizations and at least one pair of Y-axis deflection control pulses spaced apart in time by a Y-axis interval equal to a plurality of the periods between successive core energizations, said X-axis interval and said Y-axis interval being coincident in time for a plurality of the periods between successive core energizations; whereby a straight line segment is generated on the graphical display without discontinuities during the interval of coincidence.

36. A character generator according to claim 28 wherein: at least one of said storage means comprises a storage capacitor; proportioning means are provided comprising a further capacitor, proportioning switch means connected to selectively couple said further capacitor in parallel with said storage capacitor, and means to selectively actuate said proportioning switch means according to a dimension of the character to be described; whereby the dimension of the character generated on the graphical display in at least one axis is the smaller of two predetermined dimensions when said storage capacitor and said further capacitor are coupled in parallel, and the larger of the two predetermined dimensions when said capacitors are not coupled in parallel.
